ROTARY INTAGLIO PRINTING

Adolph Weiss, Brooklyn, N. Y.

Application December 7, 1932, Serial No. 646,032

49 Claims. (Cl. 101—157)

This invention relates to printing and more particularly to rotary intaglio printing; and the invention is particularly useful in printing a plurality of component parts in registered relation to each other to produce a composite impression, such as where a plurality of component color impressions are desired as in multi-color printing.

In the art of printing, and more specifically 10 in the art of rotary intaglio printing, the mechanism has been extremely bulky, largely in view of certain inherent characteristics necessary in the art heretofore, particularly where a large number of printing cylinders is desired, and this 15 results not only in consuming vast floor space but also entails other objections, in that the distance of web travel between printing cylinders is great, requiring a correspondingly great length of paper web, and accordingly in initially threading the 20 web or after breakage or other operating interruptions a great loss of paper necessarily results. Apparatus of such bulk presents the further disadvantage that operative control and adjustments are awkward and time-consuming, and 25 therefore inefficient and costly.

Furthermore in view of the inherent nature of machines heretofore employed and the manner and conditions of operating the same, printing speed has been limited to approximately 600 feet 30 per minute in monotone, and 300 feet per minute in multi-color.

Also, the servicing and proper maintenance of said machines, both during and between runs, has been difficult and time-consuming. Among these 35 latter disadvantages might be mentioned the matter of maintaining the desired supply of ink, of the desired consistency, at the printing surfaces; and keeping the operative parts free from becoming coated or gummed with ink, which when 40 partially or wholly hardened is extremely sticky.

Accordingly, an object of this invention is to provide a compact machine capable of accommodating the desired number of printing cylinders, while requiring only a relatively small floor 45 space area, and one in which a web path of travel between cylinders is reduced to a minimum, and having its operative control and adjustment means so arranged and in such close proximity that operative effort is reduced to a minimum.

Another object is to provide improved methods 50 and apparatus for carrying out the same which permits an increase in operative speed of from 100 to several hundred per cent. as compared with current practice, while producing work of the highest character.

Another object is to provide improved methods and apparatus for carrying out the same which permit extremely efficient and expeditious operative and maintenance servicing, and specifically with reference to inking and in cleaning the 5 parts subjected to ink.

Another object is to provide apparatus of the character described having means for efficiently 10 and automatically establishing and maintaining the desired web tension.

Further and more specific objects, features and 15 advantages will more clearly appear from the detailed description given below taken in connection with the accompanying drawings, which 20 form a part of the specification.

Referring to the drawings:

Fig. 1 is a side elevation showing the printing 25 end of the machine as viewed from what hereafter will be termed its control side;

Fig. 1a is a similar view showing the supply end 30 and is the complement of Fig. 1 to illustrate a complete machine;

Fig. 2 is a side elevation showing the printing end of the machine as viewed from what hereafter will be termed its drive side;

Fig. 2a is a similar view showing the supply end 35 and is the complement of Fig. 2 in illustrating a complete machine showing in general the chief drive train;

Fig. 3 is a longitudinal sectional view taken 40 intermediate the sides of the machine in a plurality of planes to illustrate details of the upper printing stage adjacent the drive side and details of the lower printing stage adjacent the control side, both as viewed from the control side;

Fig. 3a is a similar view showing the supply end 45 and is the complement of Fig. 3 in illustrating the complete machine;

Fig. 4 is a plan view of a portion of the printing mechanism illustrating one of the printing unit 50 assemblies;

Fig. 5 is a sectional view taken at 5—5 of Fig. 4 in a direction transverse the axis of the printing cylinder and showing the cylinder and related parts in elevation adjacent the center of the 55 cylinder;

Fig. 6 is a similar view taken at 6—6 of Fig. 4 adjacent the end of the cylinder;

Fig. 7 (Sheet 3) is a sectional view taken at 6—6 of Fig. 4 and is similar to Fig. 5 with certain parts omitted in order to more clearly show 60 certain features of the doctor mounting;

Fig. 8 (Sheet 3) is an elevation of certain features of a printing unit assembly illustrating 65

certain features of an ink housing and doctor mounting;

Fig. 9 (Sheet 9) is a sectional view taken approximately at 9-9 of Fig. 6 to illustrate the reciprocating mechanism for the doctor;

Fig. 10 (Sheet 9) is a sectional view taken at 10-10 of Fig. 4 to illustrate further details of said mechanism;

Fig. 11 (Sheet 9) is a similar view taken at 10 11-11 of Fig. 3, to illustrate further details of the same;

Fig. 12 (Sheet 10) is a sectional view taken at 12-12 of Fig. 4 showing particularly certain details of the printing cylinder drive train, said 15 cylinder mounting and adjustment means, pressure roller mounting and adjustment means, ink housing and chamber with inlet and outlet ports, and ink chamber float and control;

Fig. 13 (Sheet 10) is a perspective view of certain 20 adjustment details of Fig. 12;

Fig. 14 (Sheet 10) is a perspective view of a drive connection of Fig. 12;

Fig. 15 (Sheet 10) is a sectional view taken at 15-15 of Fig. 1, showing further adjustment 25 details of Fig. 12;

Fig. 16 (Sheet 11) is a sectional view taken at 16-16 of Fig. 4 showing further details of the parts illustrated in Figs. 4 and 12;

Figs. 17 and 18 (Sheet 11) are perspective views 30 of certain details of Fig. 16;

Fig. 19 (Sheet 6) is a sectional view taken at 19-19 of Figs. 2a and 3a showing certain features of the web feed drive train;

Fig. 20 (Sheet 6) is a sectional view taken at 35 20-20 of Figs. 2a and 3a showing certain features of the web tensioning brake mechanism;

Fig. 21 (Sheet 6) is a perspective view showing the said mechanism more fully;

Fig. 22 (Sheet 6) is a section at 22-22 of 40 Fig. 21;

Fig. 23 (Sheet 2) is a sectional view taken at 23-23 of Figs. 2a and 3a showing certain further features of the web feed mechanism;

Fig. 24 (Sheet 2) is a view, partly in section, 45 taken at 24-24 of Fig. 1a and showing details of the supply roll mounting and related parts;

Fig. 25 (Sheet 12) is a plan view of ink and 50 solvent reservoirs with associated parts of circulating means, taken from the approximate position 25-25 of Fig. 2 and looking in the direction of the arrows;

Figs. 26, 27, 28, 29, 30 and 31 (Sheet 12) are 55 diagrammatic illustrations of the circulating system for ink and solvent, showing the various valve settings for the respective operative liquid circuits of the system; and

Fig. 32 (Sheet 13) is a partially diagrammatic illustration of certain general features of the invention and taken in its entirety represents a 60 machine embodying four printing stages; while solid line parts of the diagram represent the machine embodying two printing stages as specifically and completely described and shown herein.

65 Referring to the drawings and more particularly to Fig. 32, the general features of the machine will first be described by way of introduction and in order to present a clear understanding of the general travel of the web and the relative location of the principal units of the present embodiment of the invention, which embodiment takes the form of a rotary intaglio printing press comprising a plurality of printing stages each of which may represent a different color.

70 As viewed in Fig. 32 the right hand side of the

diagram represents the printing end, the left hand side the supply end; the operating controls are located on the front side, and the driving means is principally located adjacent the rear side. For a more detailed structural showing of the corresponding portions as similarly viewed, reference may be had to Figs. 1-1a and 3-3a.

The web to be printed upon, such as the paper web 1 is supplied from a roll 2, from which it passes over an idle roll 3 and around a roller 4 10 which serves to hold it into engagement with initial feeding means comprising the conveyor feed belt 5 carried by the driving pulley 6 and the belt tensioning idler roller 7. From here the web passes over the roller 8 and then in a reverse 15 direction over a floating roller 9 whose position is varied according to the tension of the web to automatically vary a braking action on the supply roll; and then continues its path of travel toward the printing end of the machine.

At the printing end the web 1 passes over a roller 10, then upwardly and between the rollers 11 and 12, which are adjustingly yieldingly urged together to provide a tensioning means immediately prior to the first printing operation, 25 thence over roller 12 and beneath a pressure roller 13 which serves to urge the web into suitable printing engagement with a printing cylinder 14 to thereby make the first impression on the web at what will be termed the first printing 30 stage, designated A. The web then passes to a conveyor feed belt 15 which is supported by a driving pulley 16 and cooperating adjustable idler roller 17. This belt conveys the web around the pulley 16 and thence to a second printing stage 35 B, where a second impression is printed on the web in the desired registry with the first. For purposes of ready reference the printing unit assemblies at respective stages will be referred to hereafter as A and B in general.

As many further and subsequent printing stages C and D as desired may be employed, but for purposes of simplicity only two complete stages are fully illustrated and described in the detailed description following.

After the web has received the desired number of printing impressions, it passes from the last stage to a conveyor belt similar to the belt 15 and which will accordingly be designated 15'; and is carried by the same rearwardly and then forwardly to adjacent the printing end of the machine where it passes around rollers 18 and 19 and on to suitable disposal or folding mechanism (not shown).

The structural details of the machine will now 55 be described in particularity, first the general supporting structure, and then the remaining structure in the order of the sequence of web travel through the machine.

Frame structure

Referring more particularly to Figs. 1-1a and 2-2a, it will be seen that the structural frame in general comprises a base plate or foundation 20, the preferred construction of which may be seen in Figs. 3-3a. Vertical side frames designated in general as 21 and 22 extend longitudinally of the base 20, in spaced relation transversely thereof and lie adjacent respectively to the control and drive sides of the machine. The lower edges of the frames 21 and 22 rest in seats extending lengthwise of the base 20 at respectively opposite sides thereof and lying somewhat below the top of the base and the frames are rigidly attached to the base such as by bolts 23. The 75

frames are interconnected and braced transversely by a plurality of transversely extending members including the tie bolts or rods, such as 24, and other members which will be hereinafter referred to in connection with additional functions performed by them. The frames 21 and 22 in the present embodiment each comprises four parts, which will now be described.

The frame 21 comprises the rear portion 25 (Fig. 1a), which extends the full height of the frame 21, the lower front portion 26 (Fig. 1), the upper front portion 27, and the intermediate upper portion 28. The portions 27 and 28 are supported from the portion 26 and rest upon a shelf 29 formed on the top thereof, and are suitably secured thereto; while the rear portion 25 extends upwardly from the base 20 and is secured along its inner upper edge to the portion 28. The parts are preferably of lightened construction providing webs adapted and positioned to act as supporting and bearing points for the operating mechanism; and these and further detailed structural features of the frames will be referred to later in connection with closely related parts of the mechanism.

The frame 22 (Figs. 2-2a) is similarly constructed and comprises the respectively corresponding portions 30, 31, 32 and 33 (see also Figs. 3-3a). It is to be particularly noted that the tops of frames 21 and 22 are substantially flat, and in other respects provide shelf supports similar to 29 of frame portion 26, thereby to permit increasing the number of printing stages by adding additional stages such as C and D.

35 Main drive—Web feed

Referring to Figs. 2 and 2a, the main drive is furnished with motive power by means of the electrical motor 34 whose power is transmitted 40 through belt means 35 to the main power shaft 36 suitably rotatably journaled on the frame 22 as by journals 37-38 and extending longitudinally thereof in order to deliver power respectively to the printing and supply ends of the machine, 45 and for purposes of convenience the shaft 36 may comprise a plurality of sections interconnected in driving relationship by means of suitable couplings.

From the journal 38 the shaft 36 passes rearwardly and is journaled in a housing 39 rigidly secured to the frame portion 30 and which encloses a worm 40 secured to the shaft 36 and adapted to be driven thereby; and the worm 40 is in driving engagement with a worm wheel 41 positioned within an upwardly extending portion 42 of the housing 39 (Figs. 19 and 3a, Sheet 6). The worm wheel 41 has a hub portion 43 secured to the inner race of a ball bearing 44 whose outer race is supported in a journal cup 45 secured to the inner face of frame portion 30 (Fig. 19). A shaft 46 is freely journaled in the hub of worm wheel 41 and its ends respectively project beyond the end of the hub and the face of the worm wheel. The latter end carries a driving arm 47 whose hub is rotatably secured to the shaft 46 in driving engagement therewith. The arm 47, at its outer end, carries a releasable driving pin 48 resiliently urged into driving engagement with the wheel 41 by means of a helical compression spring 49 seated in a bore in a boss formed integral with the arm 47. The pin 48 is provided with a cross pin 50, receivable in a slot formed in the outer end of said boss, and a knurled hand piece 51 which permit the pin 48 to be withdrawn 75 from driving engagement and locked in disengaged

position by rotating the same 180° and engaging the pin 50 in a recess 52 provided on the outer face of the said boss. It will therefore be seen that the shaft 46 may be selectively placed in driven engagement with the worm wheel 41.

The other end of the shaft 46 (Figs. 19 and 3a) carries securely fastened thereto for rotation therewith a spur gear 53 in driving engagement with a spur gear 54. The gear 53 is secured to its shaft in a manner providing easy selective replacement for selectively varying its pitch diameter for reasons to be more fully pointed out hereinafter. The gear 54 is freely journaled on a stub shaft 55 which is rigidly secured to an adjustable arm 56 secured to a stub shaft 57, as by pin means; and the shaft 57 is journaled in a boss formed on frame portion 30. The gear 54 is in driving mesh with a spur gear 58 which is mounted on stub shaft 57 and freely rotatable with respect thereto.

The shaft 57 has integrally attached to its other end an adjusting lever or handle 59 which is provided with an arcuate slot and lock bolt to permit of its limited adjustable movement and its being locked in the desired position. The reason for this adjustment is that the rotational speed of the gear train at the supply end of the machine should bear a certain ratio to that at the printing end, both of which are driven from a common shaft, and such ratio must vary with different size printing cylinders in order to maintain the desired speed of web feed relative to cylinder surface speed. By the means just described a gear 53 may be provided of the desired pitch diameter, to effect said desired ratio, and by rocking the lever 59 the spur gear 54 may be suitably adjusted selectively to mesh with respective gears 53 of varying diameter, and locked in such position.

The gear 58 is in driving mesh with a gear 60 secured to its shaft 61 for rotation therewith, and the shaft is journaled in a bearing 61a which is seated in a housing formed integral with frame portion 30. The shaft 61 projects outwardly beyond the outer face of the frame portion 30 of the frame 22 and on its projecting end carries a cone pulley 62 secured thereto and adapted to be rotated thereby. The pulley 62 is engaged by a belt 63 to be driven thereby (see Fig. 2a, Sheet 4) and which passes through a belt adjuster 64 and thence around a cone pulley 65 to be driven thereby and which is tapered reversely to the taper of pulley 62 and cooperates therewith for the purpose of providing a variable speed drive. The pulley 65 (see also Fig. 23) is attached to the shaft 66 for driving the same and the shaft is suitably journaled in side frame portions 25 and 30 and carries intermediate said side frames the roller 6 which is attached thereto and adapted to be rotated therewith. The belt adjuster 64 is carried by an axially movable adjusting shaft 67 journaled in side frame portion 30 and having an end projecting inwardly of its bearing support to which is attached a screw block 68, the screw threads of which engage an adjusting screw 69 whose respectively opposite ends 70 and 71 are journaled in the frame portions 30 and 25; and the end 70 is extended outwardly through the frame portion 25 and carries secured thereto a hand wheel 72 providing means for rotating the screw 69 to thereby move the belt adjuster 64 in a direction axially of the driving pulley 62 and driven pulley 65 to thereby vary the position of the belt 63 for the purpose of effecting a corresponding variation of drive ratio between said pulleys. This speed variation not only affects the linear velocity

of the web feeding belt 5, which is carried by the roller 6 and extends substantially the length of said roller, but also affects the linear speed of the web feed conveyor belts 15 and 15', which are driven from the shaft 66 in a manner to be described following. The feed belt 5 (Figs. 1a and 23) extends around the roller 7 which is supported on plungers 73, 74 (see also Fig. 3a), which are journaled respectively in bosses provided on arms 75, 76 pivotally supported on shaft 66, and roller 7 is resiliently held forwardly of roller 6 by means of helical compression springs such as 77 (Fig. 3a) to thereby provide the necessary tautness to the belt 5 in order that the necessary driving friction might be maintained against the web to be fed between the belt 5 and its cooperating friction roller 4. The friction roller 4 is freely rotatably mounted on a shaft 78 which is suitably journaled in respectively opposite side frames, and by referring to Figs. 1a and 23 it will be seen that the shaft 78 is one of the transversely extending members which together with the tie rods 24 serve to brace the frames.

25 *Conveyor belt drive*

Referring now to Fig. 23, the drive of the conveyor belts 15 and 15' will now be described. A sprocket gear 79 is secured to the shaft 66 and adapted to be driven thereby, and carries the driving chain 80 which drives the sprocket gear 81 freely rotatably mounted on a stub shaft 82 suitably supported in the frame portion 30 and carrying a spur gear 83 integral with the sprocket 81 and adapted to be driven thereby. The spur gear 83 is in driving mesh with a cooperating spur gear 84 which is secured to and adapted to drive the shaft 85 which is suitably journaled in the opposite side frames. The shaft 85 projects outwardly beyond the frame 30 at the drive side 40 of the machine and carries a bevel driving gear 86 adapted to be driven thereby. The bevel gear 86 is in driving mesh with a corresponding bevel gear 87 which is carried by and adapted to drive a diagonally extending shaft 88 which is suitably carried in journal housings (see Fig. 2a) 89 and 90. Adjacent its lower end the diagonal shaft 88 carries secured thereto a bevel gear 91 in cooperative driving mesh with a bevel gear 92 secured to and serving to drive a shaft 93 which is suitably 50 journaled in the side frames and which carries the roller 16 which serves to drive the web conveyor belt 15. Correspondingly, the shaft 85 (Figs. 1a and 23) has secured thereto and is adapted to drive the roller 16' which in turn 55 serves to drive the web conveyor belt 15'. It will be noted from Figs. 2a and 3a that the power drive is delivered direct to the upper shaft 85 and then downwardly to the shaft 93 of the correspondingly lower unit, and that the shaft 88 60 which thus transmits the power is projected upwardly; and in this connection it is pointed out that provision is thereby made for adding additional units for additional printing stages such as C and D, heretofore referred to.

65 Before taking up the mechanism of the printing end of the machine in detail, the means for adjusting the tensioning of the conveyor belts 15 and 15' will be briefly described; but since both of these tensioning means are identical, only one will 70 be described in detail and corresponding parts of the other will be indicated on the drawings by corresponding numbers bearing the prime suffix ('). Referring more particularly to Figs. 3 and 6, it will be seen that the roller 17, which supports 75 the forward end of the conveyor belt 15, is car-

ried on the shaft 94 supported in sliding journal means 95 and adjustable in a direction transverse to the axis 94 by means of adjusting screws 96 supported in seats 97 attached respectively to the side frame members as will be more fully seen from Fig. 4. 5

Printing units

Since the printing units at stages A and B are identical in substantially all major particulars, only one of these units, i. e. that at stage A, will be described in detail and where corresponding parts of the similar unit at stage B are referred to, such as where certain parts might be clearly illustrated in sectional views in connection with unit stage B, such corresponding parts of stage B will be given the same reference characters as the parts of unit stage A supplemented by the suffix prime (') to designate the respectively different locations in the respective units of stages A and B. 10 15 20

In the present embodiment the printing cylinders, such as 14, are supported each directly by what will be termed an ink housing, and such housing and its means of support from the structural framework will first be described; and then the driving means for the cylinders and related adjustment means will be described.

The general position of the housings will be understood by reference to Fig. 1, wherein the housings are indicated in general as 98 and 98'. The said housings are supported between the side frames in a manner which will be best understood by referring to Figs. 4, 5 and 6, from which it will be seen that the housing base 99 (Fig. 6) is provided with supporting webs which are supported on the transversely extending members 100, 101 and 102, which members in turn are supported by the side frames 21 and 22 (Fig. 4). The said housing comprises ends 103 and 104 and side walls 105 and 106 (Figs. 5 and 6) 105 and 106. The housing is freely slideable axially of the members 100 and 102, which vertically support the housing, but is fastened to the member 101, which holds the housing in lateral position, (Figs. 12 and 15) as by means of set screws 107, to be moved thereby; the member 101 in turn being slideable axially on a laterally extending shaft 108. The printing cylinder 14 is positioned with a portion of its periphery extending within the said housing and is supported on a driving shaft 109, and the respective ends of the cylinder are spaced inwardly from the housing end walls 103 and 104 and the periphery of the cylinder is spaced inwardly from the side walls 105 and 106. The driving shaft 109 has a smooth sliding fit at the cylinder hub end 110 and is provided with a conical shoulder portion 111 which is seated with a driving fit in a cooperating conical bore formed in the cylinder hub end 112. The drive shaft has one end 114 supported in an inner ball race 115 whose outer race 116 is received in a bearing recess formed integral with the housing end 103 and a thrust and sealing collar 117 surrounds the drive shaft and is interposed between the adjacent cylinder hub 112 and the inner face of the race 115, serving to distribute lubricant from the bearing recess. A screw thread ring 118 is in interior threaded engagement within the said bearing bore and bears against the outer bearing race 116 to hold the bearing and the shaft carried thereby in proper axial adjustment. Similar supporting means is provided adjacent the cylinder hub 110 and the housing end 104 and such sup- 79

porting means permits the axial adjustment of the cylinder with respect to the inner faces of the housing ends 103—104. This supporting means further permits easy removal of the cylinder 14 for purposes of change of printing design or change of cylinder size. In such removal the ring 118 is removed and the drive shaft 114 may be then pulled out of the cylinder 14 in order to lift the cylinder out of the housing. To facilitate such removal I have provided sustaining lugs 119 (see also Fig. 6) on respective housing ends 103 and 104, said lugs being spaced slightly below the normal position of the cylinder hub ends 110 and 111 so that in normal operation they create no friction but as soon as the driving shaft is removed they serve to support the cylinder within the housing. The rounded upper surfaces of lugs 119 permit ink drainage. The drive shaft 109, as will be more fully pointed out following, engages its driving train by means of a sliding key connection which permits the removal above described and which furthermore permits the axial adjustment movement of the housing and cylinder now to be described.

25 *Cylinder drive and adjustment*

The housing adjustable hollow shaft 101 (Figs. 12 and 15) extends outwardly through the frame 21 and is suitably supported at its outer end in a journal housing 120 and is provided with an exterior threaded portion 121 in threaded engagement with the surrounding worm wheel screw block 122, also suitably journaled in said housing 120. The worm wheel 122 is in driving mesh with the worm 123 attached to the end of the shaft 124 and adapted to be driven thereby. The shaft 124 carries on its upper end a bevel gear 125 in driving mesh with the corresponding bevel gear 126 secured to a stub shaft 127 which is suitably 40 journaled in the frame 21 and housing 120 and is provided at its outer end with a control or hand wheel 128. It will therefore be seen that by rotating the hand wheel 128 movement is transmitted through the bevel gears, shaft 124 and the 45 worm and wheel driven thereby, causing the worm wheel 122, which is in interior threaded engagement with the hollow shaft 101, to move the said shaft axially and thereby to move the housing together with the cylinder carried thereby in 50 a direction axial of said cylinder. Axial adjustment of the cylinder is desirable for purposes of accurate registration of the design to be printed; and furthermore, circumferential adjustment of the cylinder about its axis is desirable for a like 55 reason. Means for such circumferential adjustment will now be discussed.

The shaft 108 extends outwardly beyond the housing 120 and carries, on its projecting end a hand wheel 129 by means of which the shaft may be rotated freely within its supporting hollow shaft 101. The other end of said shaft 108 projects outwardly through the side frame 22 in which it is suitably journaled for support as by a journal boss 130 and carries secured thereto a spur gear 131 which is rotated upon rotation of the shaft 108. A second control wheel 132 is secured to this end of the shaft to provide for rotation of the shaft from either side of the machine. The gear 131 is in mesh with an intermediate gear 133 (see also Fig. 2), and the gear 133 is in driving mesh with a spur gear 134 which is provided with interior screw threads in cooperative engagement with external threads of a screw sleeve 135. The screw sleeve 135 is positioned within suitable housing means 136 which

prevent rotative movement of said sleeve while permitting axial movement thereof; and said housing means also serves to restrict axial movement of the spur gear 134. The sleeve 135 is supported on a bearing 137 whose outer race is 5 clamped within a bore of said sleeve by means of a clamping ring 138. The inner race 139 of said bearing is securely clamped to the outer end of a driving sleeve 140 by means of a screw threaded ring 141. The driving sleeve 140 is 10 illustrated in Fig. 14 from which it will be seen that it is provided with an axial smooth bore 142 having an axially extending keyway in which is seated a key 143, and the exterior surface of said sleeve is provided with a steep pitch helical spline, 15 comprising in the present embodiment two grooves such as 144 and two tongues such as 145. The bore 142 is of such size as to permit a sliding fit on the driven end of the cylinder drive shaft 109 which is provided with an axially 20 extending keyway for accommodating the key 143. The helical spline on the exterior of the driving connection 140 engages a corresponding interior spline provided within the bore of a hub 146 of a driving gear 147. It will therefore be 25 seen that by rotating either the hand wheels 129 or 132, the threaded sleeve 135 is caused to be moved axially and carries with it the sleeve 140 which moves axially relative to the shaft 109 but is not restricted against rotative movement relative thereto. It will also be appreciated that since the driving gear 147 is connected to the shaft 109 by means of the cooperating helical splines of said gear and sleeve, the rotation of 30 said connecting sleeve will act to advance or retard the shaft 109, and the cylinder 14 carried thereby, relative to the driving gear 147 and its driving train. The means of circumferential adjustment of the cylinder 14 just described is primarily for the purpose of effecting 35 relatively fine adjustments; and in order to provide additional adjustment adapted for relatively more extensive or coarse adjustments, the following provision is made. The hub 146 is provided with a flange 148, to which gear teeth rings 40 149 and 150 are adjustably attached by means of screws 151; access to said screws being had through openings such as 152 provided in the housing means 136 (see also Fig. 2). By this means the gear ring parts 149 and 150 may be 45 adjusted circumferentially relative to the gear hub 146 to provide for any degree of adjustment desired. This coarse adjustment necessarily is made while the machine is shut down and serves to adjust the cylinder circumferentially to effect 50 approximate adjustment; while the fine adjustment may be effected while the machine is operating and serves to provide for accurate registration. 55

The gear 147, which is of herringbone type, (Fig. 9) is in driving mesh with a similarly formed gear 153, having a hub 154 which is journaled in a suitable bearing 155 supported by the side frame 22. The gear 153 is keyed to a stub shaft 156 60 which projects outwardly therefrom and has its outer end journaled in a bearing 157 suitably supported by housing means 158 securely but removably attached to the said supporting frame 22. The shaft 156 intermediate the bearing 157 65 and gear 153 carries a worm wheel 159 keyed thereto and said worm wheel is in driving mesh with a cooperating worm 160 which is keyed to the forward end of the main drive shaft 70 (Fig. 2). 75

Doctor reciprocating mechanism

Before describing the doctor mounting, its reciprocating mechanism will first be described since it is closely associated with the drive train previously referred to in the foregoing figure. The stub shaft 156 is provided with an inwardly extending reduced end 161 which carries pinned thereto a spur gear 162 in driving mesh with a cooperating gear 163 which is suitably journaled in a bearing 164 supported from a cover plate 165 normally forming an integral part of the housing frame 22. The gear 163 is keyed to a stub shaft 166 which extends outwardly beyond said cover plate and has its outer end journaled in a bracket housing 167 rigidly attached to the housing end wall 104. The end of the shaft 166 extends within said bracket and carries attached thereto for rotation therewith a worm 168 (Fig. 10) which is in driving mesh with a worm wheel 169 carried by an upwardly projecting shaft 170 which is also journaled in said housing bracket 167 and carrying on its upper outwardly projecting end a worm 171 adapted to be rotated thereby and in driving mesh with a worm wheel 172 which is carried by and serves to drive a stub shaft 173 journaled in a bracket 174 which is formed integral with the doctor supporting structure to be hereinafter described. The shaft 173 carries adjacent its opposite end and adapted to be driven thereby a spur gear 175 which is in driving mesh with a cooperating spur 176 carried by a suitably journaled doctor reciprocating shaft 177 which is driven thereby and which carries intermediate its ends a barrel cam 178 provided with a cam groove 179 in which is cooperatively seated a cam roller 180 which is carried on a cam pin 181 rigidly carried by the parts to be reciprocated, which will now be described in conjunction with the manner in which the doctor is mounted.

In this connection it is pointed out that the cam groove 179 is so positioned and formed as to provide a straight line motion of the doctor, i. e. so that the rate of travel of the doctor is uniform throughout substantially its full travel. This is contrary to current practice, in which the doctor reciprocations slow down considerably before reversal of direction and speed up appreciably in the middle of the stroke. The result of such motion is that during approximately one-half of the period of reciprocation the doctor knife is practically at a dwell. As a result, portions of the doctor are worn rapidly and unequally due to the unequal time of engagement of the wiping edge of the doctor with deeply etched areas of the printing cylinder which offer little or no support for the doctor. In the present invention the improved manner of reciprocating the doctor provides a uniform motion and the reduction in speed at or near the end of the stroke of the doctor before reversal is reduced to a minimum, and accordingly the doctor knife constantly changes its position with respect to the etched surface of the printing cylinder and the wear is reduced and is more uniform throughout the length of the doctor. The net result is that the doctor tends to preserve a clean wipe for a considerably longer time before it becomes necessary to rehone the wiping edge of the doctor.

In order that certain important features of the structure now to be described might be appreciated, brief reference will be made to one important phase of the invention, i. e. the provision of means for retarding the escape of

volatile ink ingredients from the ink housing in order to materially retard and preferably prevent evaporation of the ink. This is of extreme importance not only when highly volatile or rapidly drying inks are employed, as is contemplated in practicing the invention in its present preferred form, but also when relatively less volatile inks are employed, since even in relatively less volatile inks there are certain ingredients which are readily volatile, and it is the elimination or escape from the inks of these readily volatile agents which is one of the serious drawbacks in the art of printing as it is practiced in general today. In other words, it is to be clearly understood that while the present preferred embodiment of the invention contemplates the use of extremely highly volatile inks, nevertheless the invention has also proven of great merit when employed in the use of inks of the character in general use today. One of the difficulties in retarding, and more particularly in substantially preventing, the escape of volatile ingredients from the ink housing is encountered where a reciprocating doctor is employed; and since the use of a reciprocating doctor is highly desirable, if not necessary, to produce the best possible results in printing, the provision to maintain a seal with the reciprocating doctor is an important feature of the invention.

Referring again to Fig. 9 and to Figs. 5 and 6, it will be seen that the cam pin 181 is rigidly attached to a cam slide 182 which is slidably seated, as by a dove-tail connection, in a slide support 183 for movement relative thereto. The member 183 extends longitudinally of said ink housing and is provided with end flanges having a close fit with the respective end walls 103 and 104 of said ink housing; and the member 183 is provided with an outer wall flange 184 (Fig. 6) which is in close fitting engagement with a housing side wall portion 185 which is in close fitting engagement with the ink housing side wall 106 and forms an upwardly extending continuation of the same. The wall portion 185 is integrally attached to supporting arms 186 which are pivotally mounted on the shaft 102. The supporting member 183, the side wall portion 185, the ink housing end walls 103 and 104 and the side wall 106 are positioned and arranged in sealing contiguity in order to retard and substantially prevent the evaporation of ink. The reciprocable doctor slide 182 carries integrally attached thereto brackets 187 and 188 in which are respectively secured hinge pins 189 and 190 which pivotally support brackets 191 and 192 to which is secured a doctor 193 by means of the clamping members 194 and 195 and the clamping screw means 196 and 197 which are provided with knurled heads to permit ready removal of the doctor which is further held in position between its clamping bars 194 and 195 as by means of a bolt connection 198 (Fig. 4). The brackets 191 and 192 are provided with upwardly extending arms terminating in bosses serving to support respective rollers 199 and 200 which engage and are adapted to roll on respective plunger caps 201 and 202 which are urged outwardly by helical compression springs such as 203 (Fig. 6) held in position by suitable centering means and provided with adjusting means such as 204 by means of which the degree of compression may be regulated in the wiping pressure of the operating edge of the doctor; said compression means serving to urge the edge of the doctor 193 into operative engagement with the peripheral surface of the printing 75

roll such as 14 (Figs. 5 and 6). To disengage the operating edge of the doctor 193 from its contact with the surface of the printing cylinder 14, the following means is provided; referring particularly to Figs. 7 and 9. An arm 205 is secured rigidly to the reciprocating doctor slide 182 and carries in threaded engagement therewith an adjusting screw 206 which is adapted to engage a cooperating arm 207 rigidly secured to the doctor and its clamping bars (Fig. 7) by suitable means such as the screw 208. By screwing the screw 206 downwardly the shoulder thereof bears on the arm 207 causing the doctor 193 to rotate about its pivot pins 189-190 to thereby disengage the operating edge of the doctor from the surface of the printing cylinder. The doctor slide supporting bracket 183 is adjustably secured to its supporting side wall portion 185, as heretofore pointed out, by suitable clamp screws such as 209 (Fig. 5) which pass through vertical slots in the said wall portion 185 and are in screw threaded engagement with the member 183. Means for adjusting the member 183 in an upward and downward direction, such as to accommodate the position of the doctor for printing cylinders of varying sizes, (Fig. 5) comprise an adjusting screw 210 in threaded engagement with a screw boss 211 formed in the member 183 intermediate its ends and said screw being provided with a thrust spool head 212 engaged by a thrust bearing 213 which is rigidly attached to the side wall portion 185. It will therefore be seen that with the clamping screws 209 loosened, the member 183 and the parts carried thereby may be moved upwardly or downwardly relative to the side wall portion 185 by means of rotating the adjusting screw 210, which may be effected through engagement with the adjusting screw head 214. After the desired adjustment has been effected, the screws 209 are tightened to clamp the parts in desired position.

From the foregoing it will be seen that when it is desired to gain access to the interior of the housing or in the removal of the printing cylinder, the doctor blade together with its closely related reciprocating and driving mechanism which are carried by the supporting member 183, which is in turn supported by the pivoted side wall portion 185, may be swung outwardly as can best be appreciated from Figs. 8 and 10, in which the relative positions of the above mechanism in its closed and open position are indicated respectively in full and dotted lines.

The worm 171 is of sufficient length to permit proper driving mesh with the worm wheel 172 throughout the limits of adjustment of the member 183. When the wall portion 185 is swung down this driving engagement is broken, but when the wall portion is returned to operative position the driving engagement is restored.

Suitable releasable clamp means (Figs. 3, 4, 8 and 11) are provided for holding the parts closed for permitting the movement of the same and these comprise trunnion bearings such as 215 formed integral with respective end walls 103 and 104, each of said trunnion bearings having journaled therein a trunnion block 216 provided with a threaded bore to which is screw threaded clamping screw 217 provided with an outer eye end serving to pivotally support a locking cam 218 provided with a handle portion 219; the locking cam on each end of the housing being cooperatively disposed adjacent to a respective boss such as 220, one of which is positioned adjacent each of the supporting arms 186.

Further structure to effect the desired sealing of the ink housing in cooperation with parts previously described will now be pointed out, with reference particularly to Figs. 4, 6 and 9. The doctor 193 extends beyond the respective ends 5 of the printing cylinder 14 in a manner illustrated in Fig. 9, from which it will be seen that as viewed in said figure the doctor is positioned at the end of its stroke to the right. The extended portions of the doctor engage respective 10 end blocks 221 and 222 which are in respective sealing contiguity with the end walls 103 and 104 and serve to bridge the space between the said end walls and respective adjacent ends of the cylinder, thereby in effect providing inwardly 15 extending projections of said end walls. A flexible sealing strip 223 (see also Fig. 6) is clamped to the upper edge of the bracket 183 by means of a clamping strip 224 and is so formed in cross section as to be held in intimate sealing engagement throughout the length of said doctor for a substantial portion of the width of said doctor. The opposite ends of the sealing strip 223 (Fig. 9) lie sufficiently closely adjacent respective end walls 103 and 104 to effect an operating seal 25 with said end walls and the lower edges of the ends of said strip lie in sealing engagement with arcuate surfaces of the respective end blocks 221 and 222. The median portion of the lower edge of said sealing strip is cut away as at 225 in 30 order to space the edge of the same away from the periphery of the printing cylinder throughout the length of said cylinder to thereby permit and assure positive and efficient contact between the active edge of the doctor 193 and the printing 35 cylinder such as 14. It will therefore be seen that the said sealing strip and said doctor jointly serve to effectively seal the space bounded by the bracket 183, which in effect forms an inwardly extending projection of the side wall of said 40 ink housing, the end walls 103 and 104 and the end block 221, cylinder 14 and end block 222. It is to be particularly noted that this sealing condition is maintained during the operative reciprocation of the doctor.

The end blocks 221 and 222 are constructed as illustrated in Fig. 17, from which it will be seen that each block is provided with a flat end wall 226 having a cut-away portion 227 to provide a clearance for the hub of cylinder 14, and an upper arcuate wall portion 228 of a curvature similar to the curvature of printing cylinder with which the block is adapted to be used. It will be understood that the pair of blocks for use with a given cylinder are preferably especially 55 designed for the particular size cylinder with which they are to cooperate. This is desirable in order to place the inwardly projecting arcuate flanges of the blocks in proper sealing contiguity with the respective cylinder ends and to provide a continuous straight line support for the doctor and cooperating sealing strip. However, to obviate the necessity of having to change the said sealing blocks, for each and every different size cylinder, provision is made for adjusting the 60 blocks in a direction transverse the cylinder axis; so that the said straight line may be provided. This adjusting means will now be described.

Each block is provided with a suitably reinforced extension flange 229 which carries rigidly 70 secured thereto a solid block 230 which is provided with a dove-tail groove 231 in cooperative sliding engagement with a dove-tail slide 232 (see also Figs. 5, 6 and 16) formed integral with a supporting lug 233 which is rigidly secured to 75

a shelf portion 234 formed integral with the ink housing base which serves as a support for the said end blocks 221 and 222. The bracket 233 is provided with a bearing portion in which is secured free for rotation therein an adjusting screw 235 provided with an operating handle 236 and is in screw threaded engagement with a screw block portion 237 formed integral with the block member 230. It will therefore be seen that by turning the control handles such as 236 the end blocks are individually adjustable in a direction transverse the axis of the printing cylinder. In view of the size of the end blocks it is preferable to support them adjacent their overhanging ends, as viewed in Fig. 6, and accordingly the vertical walls of the end blocks are each provided with a pin such as 238 which is in sliding engagement within a horizontal slot 239 (see also Fig. 8) formed in the corresponding end wall of the housing.

The sealing member 223 functions as a sealing continuity of the housing walls proper in the vicinity of the wiping zone, serving to seal the gaps due to the reciprocal movement of the doctor knife, and it will of course be obvious that this function will be fulfilled whether the strip 223 engages the doctor knife per se or integrally attached parts reciprocal therewith; while the end seals 221—222 function as the sealing continuity of the housing frame 103—104 and serve to seal the gaps between these frames and the ends of the printing cylinder. As an additional function these parts, in their combined relationship, prevent the splashing of ink in the vicinity of the wiping zone and efficiently cause the surplus ink, which has been removed by the doctor knife, to return to the fluid chamber.

In order to effectively seal the space between the cylinder and its housing on the side opposite to that adjacent the doctor, the following provision is made, referring to Figs. 4, 5, 16, 17 and 18. A plate 240 is supported in the shelf 234 with its ends resting between the portions 230 of the end blocks 221 and 222 and fitting in undercut recesses such as 241 provided in the respective blocks 230. The plate 240 carries spaced upwardly therefrom and parallel thereto a supporting rod 242 which is rigidly attached to said plate by suitable strut means 243. A U strip 244 is pivotally supported on the rod 242 and is provided on its inner side with a clamping bar 245 between which and said strip is securely clamped a flexible sealing member 246 which is preferably made of suitable non-metallic material, more specifically felt, and is adapted to be held in light contact engagement with the adjacent peripheral portion of the printing cylinder lengthwise thereof; and the opposite ends of said strip lie closely adjacent to the inner faces of the blocks 230 of the respective end blocks 221 and 222. The strip 246 is urged into intimate sealing contact with the periphery of the cylinder by means of a flexible strip 247 extending lengthwise of and secured to the inner edge of the plate 240 and serves to normally swing the U-plate about its pivotal suspending bar 242. Carried adjacent the rear face of the U-strip 244 and toward its lower edge are a plurality of electromagnets such as 248 (Figs. 4 and 5) which when suitably energized are adapted to swing the U strip 244 in a clockwise direction against the action of spring 247 to thereby release the sealing engagement of the strip 246 with the periphery of the cylinder. In order to adjust the sealing strip in a direction transverse the axis of the cylinder, to accommo-

date cylinders of varying sizes or to properly adjust the sealing action of the strip, the following provision is made. A bearing block 249 is integrally formed with shelf 234 of the housing base structure and carries journaled therein an adjusting screw 250 provided with an adjusting handle 251 and with a threaded shank portion 252 which is in threaded engagement with a screw block 253, which block is rigidly attached to the under side of plate 240, the block 253 extending through an opening provided in the shelf 234. It will therefore be seen that by rotating the handle 251, the sealing strip and its supporting structure will be moved inwardly and outwardly in a direction transverse the axis of the printing cylinder.

From the foregoing it will be appreciated that the printing cylinder is positioned with a portion of its periphery extending within the ink housing and suitable means has been provided in combination with said cylinder and housing for effectively sealing the housing during the operation of the machine and while the doctor is reciprocating. So efficient is this sealing that the housing may be made substantially airtight, although it will be appreciated that the invention is not to be limited to the degree of sealing, since this phase of the invention will be useful in retarding evaporation to a degree commensurate with the perfection of the seal desired or effected. Referring to Figs. 5 and 6, (if desired) a splash plate or lip 254, supported on the upper edge of the wall portion 106, is provided for catching excess ink which is scraped from the printing cylinder by the doctor.

It is also to be understood that in general the invention comprises housing means for the printing cylinder which provides supporting means for said cylinder, and its wiping mechanism, accommodation for the ink, and also provides means for preventing substantial evaporation of said ink, while at the same time permitting that adjustable relationship between the various elements which is normally required in intaglio printing.

Pressure roller

Referring to Figs. 3, 4, 12 and 13, the pressure roller 13 is carried on an axle 255 having its respective ends journaled in roller bearings such as 256 which are similarly supported, and accordingly only one of the supporting means will be described in detail. Roller bearing 256 is seated in the upper end of a frame which will be designated in its entirety as 257 and the bearing is held in place by means of a bearing cap 258 and a bearing plate 259. The frame 257 is provided with oppositely disposed and spaced apart vertical sides 260 which sides or legs at their lower extremities are rigidly secured together in such spaced position by means of trunnion plates 261. The sides 260 are formed with guide flanges 260a which are seated in cooperating slideways formed in the side frames, such as 21, (Fig. 4), and the frames 257 are held in vertically slidable position in said frame by suitable strips such as 260b. The plates 261 provide bearing means for trunnion pins 262 formed integral with the trunnion block 263 which is provided with a threaded bore in which is screw threaded a jack screw 264, and said jack screw 264 has integrally formed on the lower end thereof a bearing portion 265 which is seated in a journal block 266 and is held in such journaled position in said journal block by a journal cap 267 (which is shown removed in Fig. 13 in order to more clearly illustrate the rel-

ative position of the parts). The jack screw 264 also carries adjacent its lower end a bevel gear 268 integral therewith. The journal block 266 is provided with a spindle extension 269 which is journaled within a bore eccentric to and formed within a stub shaft 270 which is journaled in its respectively adjacent side frame such as the frame 21 and which carries on its outwardly projecting end a spur gear portion 271 positioned within its gear housing 272 and in mesh with a cooperating gear rack such as 273 which is suitably slidably supported on its respective frame member such as 21 as by the supporting brackets (Fig. 1) 274 and 275.

15 It will be understood from the foregoing that the parts heretofore described and as designated on the left hand side of Fig. 12 have their counterparts on the right hand side of Fig. 12, and that by moving the pair of racks 273 a simultaneous and uniform rotative movement will be imparted to the pair of spur gears 271 and corresponding stub shafts, which being provided with eccentric bores will provide a reciprocal movement of the spindles 269, thereby imparting reciprocal motion to the jack screws 264, the angularity of which are provided for by trunnion supported screw blocks 263, and accordingly the frames 257 will be simultaneously moved in a vertical direction to thereby move the pressure roller 13 toward or away from its cooperating printing cylinder.

Referring to Fig. 1, means will be described for mechanically interconnecting the pair of gear racks 273. The cross shaft 100 (see also Figs. 2, 35 4 and 16) extends transverse the side frames of the machine and suitably journaled therein and carries adjacent each side frame a gear sector such as 277 secured to said shaft and adapted to be rotated therewith. Said gear sectors are in driving mesh with respectively cooperating gear racks 273, and accordingly the movement of one gear rack will be transmitted to the other so that the two will be moved in synchronism. Motion is given to the gear rack 273 adjacent the control 40 side of the machine (Fig. 1) by means of a spur gear 278 in mesh with said rack adjacent its forward end and said spur gear is mounted in a spindle shaft suitably journaled on the side frame adjacent thereto and is provided with an operating handle 279 which serves to furnish means for manual operation to raise and lower said pressure roller. For purposes of facilitating the operation of the machine, power means for raising and lowering the pressure roller is also provided, 45 which will now be described with reference to Fig. 1.

An operating bar 280 carries at its forward end a connecting block 281 which carries a horizontal pivot pin 282 serving to interconnect a cooperating connecting block 283 which in turn is attached to the rear end of the gear rack 273. Attached to the rear end of the bar 280 is a gear rack 284 which is in mesh with a spur gear 285 secured to a clutch hub 286 and suitably journaled in a bracket 281. A power shaft 288 passes freely through the gear 285 and its clutch hub 286 and is suitably journaled adjacent its lower end in a supporting bracket 289 and carries at its lower end a worm wheel 290 positioned within a housing 291 and in mesh with a worm 292 attached to a shaft 293 which is driven by a suitable source of power such as an electric motor (not shown). In this manner the shaft 288 is rotated and is interconnected to the shaft 280 by means of a 50 clutch collar 294 which is freely slidably axially

of the shaft and is rotatably connected to the shaft as by a key. The clutch collar 294 is provided with clutch teeth 295 adapted for driving engagement with the clutch hub 286 by means of cooperating recesses formed in the driven clutch 5 member. The clutch collar 294 is provided with a groove into which extends a pair of trunnion pins such as 296 integrally formed on a clutch lever 297 pivotally supported from the frame 21 at 298 and provided with a downwardly extending 10 integrally formed crank end 299 having a detent pin 300 adapted to engage in a detent recess 301 formed in the frame for locking the clutch mechanism in disengaged position. From the foregoing it will be seen that by lifting up the right 15 hand end of the clutch lever 297 power is transmitted from the power shaft 288 through the clutch to the spur gear 285 causing the latter to move to the right and thereby transmitting power to the forward gear rack 273 and simultaneously 20 through the gear sectors 277 and the cross shaft 100 to the corresponding gear rack on the opposite side of the machine; and this results in simultaneous movement of the gear racks 273 forwardly, which causes a rotation of the eccentric 25 journals on the shaft 270 and accordingly a simultaneous raising of the side frames 257 and the lifting of pressure roller 13.

The following provision is made for adjusting the pressure roller 13 into parallelism with the 30 printing cylinder surface, and for compensation for varying printing cylinder diameters which is conveniently brought about by independently raising or lowering one or the other of the journal bearings of the printing roller in the following 35 manner. Referring particularly to Figs. 12 and 13, a shaft 302 is suitably journaled in the lower extremities of journal blocks such as 266 and extends transversely of the machine. The shaft 302 carries secured thereto for rotation thereby bevel 40 gears 303 and 304 respectively in mesh with the pair of bevel gears 268. One of the bevel gears such as 303 is selectively secured to its shaft as by the set screw 305, while the other bevel gear 304 is permanently secured as by the pin 306. 45 One end of the shaft projects outwardly beyond its respective journal block 266 and is provided with a hexagonal end 307 providing means for engaging said shaft with a suitable socket wrench. Accordingly it will be seen that by rotating the 50 shaft 302 and the gears 303 and 304 carried thereby, the supporting bearings of the pressure roller are adjusted to cause the pressure roller to be moved in parallelism with the desired variation in pressure or adjustment to provide for cylinders 55 of different diameters. Furthermore, by releasing gear 303 from the shaft and rotating the shaft 302 in the direction desired, the proper alignment of the pressure roller with respect to the printing cylinder may be readily effected. 60

Web tensioning means

Before proceeding with a detailed description of the ink supply and circulating system, a description of the mechanism for adjusting and 65 maintaining the proper tension in the web to be printed upon will now be given, with reference to Figs. 2a, 3, 3a, 20, 21 and 22. After the web of paper leaves the web feeding means, which will be designated by the roller 4 and cooperating 70 feed belt 5, it is fed forwardly over the idle roller 8 and rearwardly over the roller 9, which will be termed the slack-tension roller, and then forwardly over roller 10 carried on the shaft 102 and then between the rollers 11 and 12. It is 75

between these rollers 11 and 12 at the printing unit on one hand and the feed roller 4 and cooperating feed belt 5 on the other hand that the automatic tensioning device now to be described 5 is positioned and is adapted to function in normal operation. The slack-tension roller 9 (Figs. 1a and 3a) is journaled adjacent its respective ends on bearing carriages such as 308, each of which is slidably supported on a track 309; it being understood that respective journal carriages and related tracks are positioned respectively adjacent relatively opposite side frames of the machine, but for purposes of simplicity only one unit will be described in detail. Each bearing carriage 308 is provided with depending side walls which serve to retain it in position on its track relatively opposite the ends of a torque shaft 310, each end of which carries an equalizing spur gear 311 in engagement with its respective track 309, thereby assuring an equalization of movement of the pair of bearing carriages 308 in order to maintain a movement of parallelism of the roller 9. The carriages 308 are attached respectively to flexible straps such as 312, which are secured to 25 and partially wound around respective spools such as 313 (Fig. 21) secured on respectively opposite ends of a shaft 314 which shaft also supports the roller 3 which is freely rotatably mounted thereon. The shaft 314 extends outwardly 30 beyond the side frame 21 and carries on its extended end a spring drum 315 freely rotatably journaled thereon and held in position by a collar 316. The drum serves to house a convolute spring 317, one end of which is attached to the shaft 314 and one end to the housing 315. Means for adjusting the tension of the spring 317 is provided by a hand wheel 318 (Fig. 1a) which serves to rotate the spur gear 319 in mesh with gear teeth 320 formed on the periphery of 40 the drum 315. A detent latch 321 is provided for retaining the housing 315 in the desired adjusted position in which it has been set by the rotation of handle 318 to provide the desired spring force. It will therefore be seen that the spring 317 urges the drum 315 to impart the desired tension to the straps 312 for exerting the desired pull on the slack tension roller 9.

A weight adjusting connecting link 322 (Fig. 21) has its forward end engaging shaft 310 and 50 its rear end engages a roller stud 323 axially journaled in a roller 324 and from which is suspended a fulcrum weight 325. The roller 324 is provided with a grooved periphery in rolling engagement on a track 326 which is formed as an integral 55 part of a fulcrum bracket 327 provided with a fulcrum stud 328 suitably journaled in the rear frame portion 30 of the side frame 22 (see also Fig. 2a) and projecting beyond the outer side thereof. On the outwardly projecting end of the 60 fulcrum stud 328 is secured a pinion gear 329 adapted for rotation therewith, and said gear 329 is in driving mesh with a spur gear 330 carried by a stub shaft 331 suitably journaled in said frame portion 30. A pendulum arm 332 is suitably attached to said gear 330 suspended therefrom and adapted to be oscillated thereby. A suitable knuckle joint 333 is provided (Fig. 22) with swivel connected sleeves 334 and 335; the former freely slidably engaging the pendulum 65 arm 332 and the latter engaging a downwardly extending arm 336 to which it is secured in adjusted position by a thumb screw 337. The arm 336 serves as a brake pressure arm and is formed integral with a journal bracket 338 supported on 70 and adapted to be rotated about a stub shaft 339

carried by and projecting outwardly beyond the frame portion 30. The bracket 338 is provided with a journal bore, extending transverse the shaft 339, and in which is freely rotatably journaled a fulcrum shaft 340 provided with a screw shank 341 in cooperative threaded engagement with a fulcrum weight 342, the position of which is adjusted along the arm by means of a hand wheel 343 integrally attached to the shaft 340.

A brake pressure link 344 has one end pivoted 10 to the arm 336 and its other end pivoted to one end of a brake band 345 whose other end is pivotally supported from the frame portion 30 as at 346. The band is in cooperative encircling engagement with a brake drum 347 (Figs. 2a and 15 24) secured to an outwardly projecting end of a brake shaft 348 suitably journaled in the frame portion 30 and whose inwardly projecting end carries secured thereto, and driven thereby, a pinion gear 349 in driving mesh with a spur gear 20 350.

The gear 350 is carried by a web roll axle 351 and is suitably connected thereto to be driven thereby, as by a key, to provide relative axial sliding movement between said gear and axle; 25 and said gear is restricted in axial movement by means of a flange on the gear 349. The axle is supported in journal notches formed in the respective side frame portions 25 and 30 (Figs. 1a and 24) and has one end projecting outwardly 30 beyond the frame portion 25. On said projecting end is secured a flanged collar 352 which is engaged by a cooperating adjusting fork 353 which is journaled on and supported by an adjusting screw shaft 354 whose inner end is in 35 screw threaded engagement with a cooperating screw thread formed in the frame portion 25, and whose outer end carries a hand wheel 355 for rotating said screw. The fork 353 is also provided with a guide pin 356 slidably seated in a bore in 40 the frame portion 25.

Having described the mechanism for varying the slack-tension and the brake means for resisting the unwinding of the supply roll 2 (Figs. 1 and 1a), the means of applying web tension adjacent the first printing stage, as between the guide roller 12 and pinch roller 11, will now be described.

A pair of supporting brackets 361 are rigidly attached to and supported from the respective side frame members (Figs. 1, 2, 3 and 4) 22 and 21 and are each provided with a bifurcated bearing end 358 between which bifurcations is seated a knurled adjusting ring 359 in which is screw threaded an adjusting screw 360 provided with a bifurcated upper end 361. A roller axle shaft 362 is provided with square ends such as 363 which serve to support the shaft 362 and prevent the same from rotation. The shaft 362 carries freely journaled thereon the guide roller 12; and the shaft supports adjacent respective ends of the roller 12 brackets 364 which are rigidly attached to their supporting shaft and extend forwardly thereof (Fig. 2). Each of the brackets 364 is provided with bifurcated forward ends, between which are supported a slide block 365 65 adapted to slide in a direction transverse the axis of the shaft 362. The slide blocks 365 serve to journal respective ends of an axle 366 to which is integrally formed the pinch roller 11, the surface of which is formed of some resilient material such as rubber. The blocks are each provided with a forwardly extending screw stem 367 surrounded by a compression coil spring 368 and a cap plate 369 which is secured to the bifurcations of brackets 364 serves to hold the compres- 70 75

sion spring in position. A threaded handwheel such as 370 serves to limit the rearward movement of the journal block 365.

The end of the axle 366 adjacent the control side of the machine extends outwardly beyond the bracket 364 (Fig. 4) and carries pinned thereto a friction plate 371 provided with a suitable friction face adapted for engagement with a friction plate 372 which is freely journalled on the axle 366 and is prevented from rotation thereon by means of its rearwardly extending end which is provided with a bore through which the shaft 362 passes. A second friction disc 373, adapted to engage the friction plate 372 and provided with a suitable friction face, is mounted on the axle 366 and is attached thereto by suitable means such as a key to cause the disc to be driven by the axle shaft while permitting relative longitudinal movement thereon. A compression coil spring 374 surrounds the outwardly projecting end of the axle 366 and engages the hub portion of the disc 373 and is held in compression by means of a knurled nut 375 carried on the threaded end 376 of the axle 366. It will therefore be seen that by adjusting the nut 375, the spring 374 urges the friction disc 373 into engagement with the friction plate 372 which in turn is moved into braking engagement with the cooperating friction disc 371, thereby creating frictional resistance against the rotation of the pinch roller 11, which is caused to rotate by the feed of the web between the rollers 11 and 12 due to the pull on the web caused by its engagement with the printing cylinder 14 against which it is held by the pressure roller 13.

It will therefore be appreciated that by suitably adjusting this braking means and the braking means previously described for creating unwinding resistance at the supply roller, the feed conditions at respective ends of the machine may be properly adjusted; and the intermediate slack-tension adjustment cooperates with these two tensioning means in order to maintain a uniform tension of the web during operation. The co-operative function of these three co-related means will be better understood from the operation of the mechanism which will be discussed following the description of the remaining mechanical features of the machine.

Ink and solvent supply and circulation

As an introduction to the description of the means of supplying and circulating the ink and solvent, which forms an important part of the invention, the broader aspects of the same will be briefly pointed out. Solvent reservoir means and ink reservoir means are provided for each of the printing units, so that the ink supplied to the individual printing units may be kept separate and distinct each from the other, to thereby provide for inks of different characteristics, such as inks differing in color, for the respective printing stages. The reservoir means are sealed in to prevent contamination and evaporation of the volatile ingredients and said reservoir means are in sealed communication with the ink housing which provides at its bottom portion a chamber for the operating ink. As has been heretofore pointed out, the housing in the preferred embodiment of the invention is adapted to be closely sealed. Therefore the entire circulating system is enclosed in an efficient manner and, as will be more fully appreciated from the following, the ink circulated in a manner to produce a continuous and efficient uniformity of ink for application to the printing cylinder. The means em-

ployed also permits an efficient method of flushing out the entire ink circulating system with solvent to maintain the parts in a clean state.

Referring more particularly to Figs. 1 and 2, it will be seen that in the present detailed embodiment of the invention employing two printing stages, two tanks are provided, one for each printing unit; but since the respective tanks are identical in construction and interconnection with their respective units, only one tank and its interconnecting means will be described in detail. The tanks such as 377 are mounted on the bed plate or base 20 and extend transverse the same between the side frames 21 and 22; the tanks being of such width that they may readily be inserted and removed between the openings in the side frames for purposes of convenience in manufacture, assembly and replacement or exchange. Each of the tanks is provided with a longitudinal extending partition 20 (Fig. 3) 378 which serves to divide the tank into two liquid-tight compartments 379 and 380 for the accommodation of ink and solvent respectively. The tank bottom 381 is inclined from the control side of the machine toward the driving side (from frame 21 to frame 22) so as to provide a low point in each tank compartment adjacent the drive side of the machine for outlet openings.

Referring to Fig. 25, the outlet opening from the solvent compartment 380 is in communication with a two-way valve 382, which has its outlet port connected to one end of the pipe 383; whose other end is connected to the inlet side of a three-way valve 384 whose other inlet port 35 is connected to the outlet port of the ink compartment 379 and whose outlet port is connected to one inlet port of a second three-way valve 385. The valve 385 has its other inlet port connected to an L-pipe 386 and its outlet port to 40 a union connection 387 which is connected to the intake port of a liquid pump 388, which is supported (Fig. 2) on a suitable bracket 389 rigidly secured to the base plate 20. The discharge port of the pump 388 is connected to a 45 three-way valve 390 which carries attached thereto a vertical pipe 391 whose upper end is connected to a flexible liquid conduit 392, whose upper end 393 (Figs. 5 and 6) is connected to a horizontal feed pipe 394 which extends through 50 the side frame member and through the ink housing supporting structure beneath the ink housing base 240 substantially parallel to the adjacent side wall of the ink housing and extending substantially the length of said housing. 55 A plurality of branch feed pipes 395 are connected to the feed pipe 394 (see also Fig. 12) and have their discharge ends in suitable liquid-tight engagement, as by threading, in the lowermost portion of the bottom wall of the ink housing; the bottom region of said housing serving as an ink chamber. As will be seen from Fig. 12, the bottom of said chamber inclines from the housing end 104 downwardly toward the housing end 103 and the bottom portion of said chamber provides a sump region such as 396 (Figs. 5 and 3). Referring more particularly to Figs. 2 and 1, adjacent the housing end 103 the lowermost portion of the sump 396 of the ink chamber is provided with a drain outlet 397 into which is removably seated an overflow pipe 398 which extends upwardly into the fountain chamber to a height equal to the desired liquid level in said ink chamber as predetermined according to the diameter of the printing cylinder and the portion 70 75

of said cylinder to be immersed. The drain outlet 397 is suitably connected to the upper end of a flexible liquid conduit 399 (Figs. 3 and 1), whose lower end is suitably connected to a three-way valve 400 which is secured to the top of the tank 377 with one of its outlet ports in communication, such as at 401, with the interior of the ink reservoir 379 at (Fig. 25) the uppermost portion of said reservoir and adjacent the end of said reservoir opposite to the outlet port previously described. The other outlet of the valve 400 is connected to a suitable fluid conduit 402 provided with an outlet opening 403 in communication with the solvent reservoir 380 and positioned adjacent the top and end of said reservoir diagonally opposite from the outlet port of said reservoir.

Circulating pump and float control means

Referring to Figs. 2 and 2a, the pump 388 is provided with a drive pulley 404 which is connected by means of a belt 405 to a cooperating drive shaft pulley 406 secured to a drive shaft 407 for rotation therewith. The shaft 407 extends longitudinal of the machine and is suitably journaled on the exterior of frame 22. The drive shaft is driven by suitable power means such as the electrical motor 408 which is suitably supported from the side frame 22 whose input power lines 409 are connected to electrical power lines by suitable control devices (not shown). Suitable additional operating control means are diagrammatically illustrated in Fig. 2a and the structural details of the same will be more fully pointed out following.

Referring to Fig. 3, a cross pin 410 is suitably journaled in the housing base frame as by being journaled in the housing end wall 103 within the ink housing and one end of said pin projects outwardly beyond the end wall 103 (Fig. 4). Said pin serves as a support for a float arm 411 which is fixed integrally thereon adjacent the inner face of the end 103 (see also Fig. 12) and adapted to be rotated thereby. The inner end of the arm 411 carries a float 412 so positioned that it will be raised when the liquid level from the ink chamber rises to a height substantially above the overflow pipe 398. The outer end of the pin 410 extends beyond the housing end 103 and carries pinned thereto for rotation thereby a contact arm 413, on the outer end of which is carried a suitable contact pin 414 suitably electrically insulated and provided with upwardly and downwardly extending contacts points. A cooperating contact pin 415 is positioned above the upper end of the pin 414 in cooperative alignment therewith and is suitably supported from the end wall 103 from which it is suitably electrically insulated. A third contact pin 416 is positioned beneath the lower end of pin 414 in cooperative alignment therewith and is also suitably supported from the end wall 103 from which it is suitably electrically insulated.

Referring to Fig. 2a, it will be seen that the pins 414 and 415 are connected in contact series to one side of the power input line 409, and the pin 416 is connected to the other side of the line 409 in series with a suitable signal device such as a bell 417. The contact points are so adjusted that when the float 412 is in its normal or lowermost position the contact points 414-415 serve to close the input lines to the motor 408, so that said motor will operate to drive the circulating pump; and if the ink level should rise appreciably above its predetermined height within the ink chamber, such as by possible obstruction in the return line to the ink reservoir, the float will be

raised to lower the contact pin 414 into engagement with the contact pin 416 which will serve the joint function of interrupting the electrical energy to the motor to thereby cause the same to interrupt the operation of the circulating pump, and at the same time the alarm bell 417 will be energized to warn the operator of the obstruction in the circulating system in order that this defect may be remedied.

Air conduit and web threading means

Referring to Figs. 2, 2a, 1 and 3, each of the printing stages is provided with air supply means and cooperating mechanism associated with respective conveyor belts 15 and 15'; since these are similar in construction and operation such mechanism will be described in detail with respect to stage A only, and the major parts of the corresponding mechanism of stage B will be indicated by similar numerals followed by the prime suffix ('). A suitable electric motor blower unit is designated in its entirety as 418 and is supported on a suitable bracket means 419 supported from the side frames 21 and 22. The blower unit is provided with a fan blower 420 enclosed in a suitable housing, to which is attached an air conduit 421 which extends transverse the machine substantially coextensive with the width of the conveyor belt 15. The said conduit is provided with air ducts or louver openings 422, which are also coextensive with the width of the belt 15, and the air duct 421 lies adjacent the under side of the belt 15 and continues around that portion of the belt passing over the roller 16, to thereby direct successive streams of air crosswise of the belt and spaced successively along the path of travel of the belt as it passes around said roller 16. The air supply thus delivered serves to assist in threading the web through the machine by holding the free end of the web up against the belt 15 and directing its travel against and with the belt around the roller 16; it also serves during the operation of the machine to prevent the flutter of the web with respect to the belt 15, and further serves to insure rapid drying of the ink impressions on the under side of the web as they leave the printing cylinder. In order to further assist in threading the web through the machine an idle roller 423, suitably journaled on respective side frames of the machine and extending transversely therebetween, is positioned with its periphery in contact with the inner face of the belt 15. A cooperating roller 424 is suitably journaled on a shaft 425 which is supported on a pair of arms 426 which lie adjacent respective side frames and are mounted on and secured to a torque shaft 427, one end of which projects outwardly beyond the side frame 21 and carries secured thereto a dependent arm 428 (Fig. 1). The arm 428 is provided with a bifurcated end 429 which straddles bar 280 and on its forward face abuts a collar 430 pinned to said shaft and is held thereagainst by a helical compression spring 431 positioned around said shaft and retained in place by means of a collar 432 pinned to said shaft. It will therefore be seen (Fig. 1) that the roller 424 may be raised upwardly to cause the forward end of the web being fed through the machine to engage with the under surface of the conveyor belt 15. The reason for interconnecting this raising mechanism with the bar 280 is to insure that at such times as the web is thus engaged with the conveyor belt 15, the pressure roller will be raised from its cooperative position with the printing cylinder; it being understood that the

roller 424 is only brought into operative position during the threading of the web, at which time it is not desired to have the web fed by means of the printing cylinder and cooperating pressure roller.

Additional printing stages

Before describing the manner in which provision is made for readily adding printing stages 10 additional to A and B, it will be noted (Figs. 2, 9, and 11) that the drive of the printing unit of stage B, i. e. for driving the printing cylinder and doctor, instead of being taken directly from the drive shaft 36 is taken from the intermediate 15 gear 147 (Fig. 11) which is in driving mesh with the herringbone gear 433, corresponding to the gear 153 of stage A (Fig. 9) and similarly formed, secured to a stub shaft 434 journaled in the side frame portion 32 and cooperating housing means 20 435 integrally attached thereto. The stub shaft 434 carries a pinion gear 436 (see also Fig. 3) attached thereto and in driving mesh with an idle gear 437 which is suitably journaled on the stub shaft carried in the frame portion 32 and is 25 in mesh with a spur gear 438 suitably journaled in the frame portion 32 and in driving engagement with the doctor reciprocating mechanism drive shaft 166 as by key means permitting axial movement of said shaft. The gear 433 is in 30 driving mesh with gear 147 which, as will be now understood, serves to drive the printing cylinder 14 of stage B. It will also be understood that in adding subsequent stages the gear such as 147 serves to deliver driving power to the succeeding stage, and so on.

Referring to Figs. 1, 1a, 2, 2a, 3 and 3a, it will be understood that the driving train such as just described including the gear train mechanism which will be designated as 433—147, and 40 cooperating mechanism comprising the printing unit of stage B, are mounted on and carried as a unit by the corresponding and oppositely disposed upper forward side frame portions 21 and 32 and interconnecting tie members in such manner that a unit of this character may be mounted in its entirety on the upper edge or shelf portion of stage B to provide, for example, additional stages such as C, D, etc. It will also be understood that the conduit and web threading means 45 just described, as well as the cooperating conveyor mechanism and drive means therefor for stage B are carried as a unit on the respectively opposite upper intermediate side frame portions 28 and 33 and interconnecting tie members and 50 form, in conjunction with the printing unit just described, a self-contained unit which unit may be duplicated in superimposed position to form succeeding stages such as C, D, etc. The conveyor drive mechanisms of succeeding stages, as 55 has been previously pointed out, are supplied with power from the drive shaft 88 (Fig. 2a); and similarly the shaft 288 (Fig. 1) is adapted to be extended for interconnection with succeeding stages to furnish power drive for the movement 60 of the pressure rollers and the web threading rollers such as 424. It is of course understood that when additional stages are added, correspondingly additional reservoir means and interconnecting conduits will also be added, so that 65 a machine incorporating a number of stages in excess of two will be as complete in all details as the specific embodiment described here in detail, comprising stages A and B; the invention presenting a combination and arrangement 70 of parts so grouped and coordinated as to read-

ily provide for unitarily building up to the desired number of stages.

Operation

The method of practicing the invention, with particular reference to the operation of the apparatus herein described, will now be pointed out. It will be assumed that apparatus constructed and arranged as previously described and adapted to operate in the manner to be pointed out is to be set up for printing on a continuous web of paper a series of composite impressions comprising two component unitary impressions or designs, which component impressions are to be printed at the respective stages 15 A and B, each in a color differing from the other; and further that the respective printing rollers of the desired size have been provided with a printing surface comprising what will be termed engraved and unengraved portions in a manner 20 to produce the desired impressions. Accordingly, a description will first be given of the manner in which the printing cylinders are inserted within the ink housings in cooperative assembled relation to their respective drive shafts, and 25 after this has been set forth the manner of threading the web through the machine and setting up the machine for operation will be described.

Referring more particularly to Figs. 8, 5, 6 and 30 12, the handles 219 are operated to release the cam latching mechanism and the side wall portion 185 of the ink housing is swung outwardly about its pivot point 102 to place the same in open position. The pressure roller 13 is removed 35 and (Figs. 6 and 12) the end blocks 221 and 222 are removed and the U-strip 244 and the parts carried thereby comprising the sealing shutter are removed, to thereby obtain ready access to the housing. Next the printing cylinder 14 (Fig. 40 12) is positioned within the housing and is supported upon the lug extensions 119 formed integral with the end walls 103—104, with the tapered bore 111 adjacent the end wall 103.

The cylinder drive shaft 109 is then inserted 45 through the opening in frame 21 with its driving end in advance of its tapered end and is inserted through the journal recess in end wall 103, through the cylinder 14, through the journal recess in end wall 104, through the cooperating bore 50 142 in the drive connection 140 with its keyway in driving engagement with the key 143. When the tapered portion of the shaft 109 engages its cooperating bore in hub 111 a sharp blow is delivered to the end of the drive shaft to firmly lock 55 the said shaft and printing cylinder. In this connection it is also pointed out that the end 114 of the shaft is provided with screw threads adapted to be engaged by a suitable nut wrench for the purpose of unlocking the shaft from its locked 60 engagement with the hub of the printing cylinder when it is desired to remove the said cylinder.

The pressure roller 13 is now returned to its journaled position on the upper end of its supporting frame 257 and after being secured in position is adjusted to the desired pressure contact relative to the surface of the printing cylinder. The end blocks 221 and 222 are inserted in position and the printing cylinder is adjusted so as 70 to provide a running clearance with said blocks while being in sealing contiguity therewith. The overflow pipe 398 is now inserted in the outlet opening 397, the side wall portion 185 with the parts carried thereby is swung upwardly (Fig. 8) 75

into closed position where it is locked by means of the cam latches 218.

The doctor bracket 183 is now adjusted so as to position the operating or wiping edge of the doctor knife 193 in close proximity to the surface of the printing cylinder and the ink chamber is supplied with the printing fluid. After this the printing cylinder is coated with ink and the operator adjusts the doctor to its proper wiping pressure until a clean wipe is secured. The sealing shutter 244 is now returned to its operative position and is adjusted in proper contact with the printing surface.

At this point it will be noted that the ink housing has been effectively sealed through the cooperation of the housing, the printing cylinder, the doctor and the inwardly projecting extensions of the housing such as the end blocks and the doctor bracket, supplemented by the flexible doctor seal and the sealing shutter; to thereby prevent the evaporation of the ink, i. e. the escape from the housing of the volatile ingredients of the ink.

The corresponding parts of the next printing stage, and all succeeding printing stages which might be employed, are correspondingly positioned and adjusted and the printing units are now ready to receive the web to be printed upon.

The web roll 2 (Figs. 1a and 24) is now placed on its axle 351 with the gear 350 in the position shown and the axle is placed in position in the supporting notches provided in the respective side frames 21 and 22, as indicated in Fig. 24. The hand wheel 355 is operated to adjust the web 1 in the desired lateral position in the machine. The web is now manually unwound from the roll 2 and is looped around the guide roller 3 (Fig. 3a) and placed between the roller 4 and the unwinding feed belt 5, which is provided with an outer surface covering, preferably rubber, having tractive characteristics and serving to feed the web forward when the same is held in pressure engagement therewith by means of the roller 4, to thereby unwind the web from roll 2. If desired, the web unwinding mechanism may be now operated intermittently to provide the supply of web necessary for further feeding. The web is now passed forwardly around the guide roller 8 (Fig. 3), and rearwardly over the slack-tension roller 9, and then forwardly around the guide roller 10 (carried on the shaft 102), over the aligning guide roller 12 while the pinch roller 11 is disengaged by means of nut 370, and thence under the pressure roller 13, which in normal printing position serves to hold the web in printing engagement with the printing cylinder 14 to thereby impart a propelling action to the web during printing; but which at this time is in its raised position. The point of engagement between the surface of the printing cylinder and the under side of the web will be referred to as the printing zone.

From the printing zone the web is fed rearwardly to the conveyor belt 15 and between the lower face of the belt 15 and a cooperating supporting plate 424a, on which the leading edge of the web is then made to rest, with its forward end projecting beyond the axis of the roller 424. The conveyor belt 15 is now placed in operation, and the blower 420 is started and the roller 424 is raised by means of the connecting link (Fig. 1) 428 which is operated by the bar 280 which serves to insure a simultaneous raising of the pressure roller 13, and this may be accomplished either by the manual control lever 279 or the power control lever 297. It will be understood that the

power operation of the bar 280 in either its forward or rearward direction is in interconnection with the power shaft 288 which is rotated by a suitable electric motor (not shown) and that the direction of movement of the said bar and its interconnected gear racks will be determined by the direction of rotation of said electrical motor, which accordingly is adapted to run in either direction. Furthermore, a suitable control device (not shown) is utilized for the purpose of enabling the operator to start or to stop the motor as well as to determine its direction of rotation. Furthermore, in order to limit the forward and rearward movement of the racks 273 operated by the bar 280 and to insure uniform pressure between the pressure roller and printing cylinder according to the adjusted setting of the pressure roller, suitable stop pins 273a and 273b are secured to the respective rearward and forward ends of the rack 273. In this way uniformity of contact pressure is always secured between the pressure roller and cylinder without requiring any adjustment by the operator when he raises or lowers the pressure roller 13. The raising of the roller 424 engages the web resting on the shelf 424a and raises the web into contact with the lower face of the conveyor belt 15, this being permitted by a suitable clearance opening provided in the shelf 424a. At the highest point of its position the roller 424 exerts a yielding pressure to hold the web against the belt by means of the resilient interconnection on the lower end of the roller connection 428 through the coil spring 431. The conveyor belt 15 thereby starts to feed the web rearwardly and the moving end of the web is further held in frictional engagement with the under side of the belt 15 by means of the air blasts from the air conduit 421. Accordingly, the web is fed along with the belt 15 around the belt roller 16 to the upper travel of the belt 15, and the leading end of the web is returned to the operator adjacent the printing unit at stage B.

The operator next conveys the leading end of the web 1 through the printing unit at stage B 45 in accordance with the manner previously described in connection with the first printing unit and after the web has passed between the co-operating pressure roller 13' and printing cylinder 14', it is similarly carried around by the conveyor belt 15' and thence forwardly toward the front of the machine, from where it may be taken to additional printing units in a like manner. From the last printing unit the web is taken around rollers 18 and 19 to a disposal point (not shown), such for example as a folding device. It may be pointed out at this time that the web engaging surface of the conveyor belts such as 15 is treated to be relatively smooth and of such character as not to possess any appreciable inherent tractive surface; the purpose of this being to prevent an undue tensioning of the web or tearing of the web at this point, since in normal operation the web is fed through the machine at the printing units by the rotation of the printing cylinders. Also, during normal operation the conveyor belts serve as moving supports for the web during the printing operation to assist in the maintenance of a constant uniform tension of the web at the printing units, 70 by relieving the web of varying friction during the longest part of its relatively free travel, and further the air blasts utilized in conjunction with each web serve to hold the same against the web to prevent fluttering of the web. It is also 75

pointed out at this time that the air blast serves the additional function of expediting rapid drying of the printed surface of the web.

After the web is threaded through the machine 5 as previously described, the operator proceeds with the adjustment in order to synchronize the surface feeds of the web at various points and this entails the driving speed adjustment as well as the adjustments of the brake tensions at the 10 supply end of the machine and at the printing end of the machine; all of which will now be more fully described.

To impart the requisite tension to the web at the printing end, for guiding and registering 15 purposes (Fig. 4) the pinch roller tension mechanism previously described is adjusted. During the previously described web threading operation, the pinch roller 11 is spaced away from the co-operating roller 12 by means of the knurled nuts 20 310. Accordingly, the nuts 310 are now screwed outwardly to permit the springs 368 to force the pinch roller 11 against the web to cause the same to be resiliently engaged between the rollers 11 and 12. The pinch roller brake mechanism 25 is now adjusted to the desired degree by means of the screw nut 315 to thereby provide the desired tension as the web is propelled by the printing cylinder 14 against which it is held by the pressure roller 13.

30 The web roll 2 (Fig. 1a) exerts a certain resistance which will be termed unwinding tension against the pulling force of the unwinding feed belt 5, but due to its momentum, however, the web roll 2 when in motion will tend to freely 35 unwind when the machine is brought to a sudden stop. To prevent such an occurrence a brake tension is applied to the supply roll axle 351 by means of the brake drum 347 and cooperating brake band 345 and interconnecting means previously described. The operating pressure for 40 said brake means is transmitted to the brake by means of the connecting link 344, and the initial pressure on said brake is regulated by the hand wheel 343 which serves to shift the weight 342 on its fulcrum arm 341. It will thus be seen that 45 the brake pressure increases the unwinding tension of the web roll 2 and is in direct ratio to the pressure force exerted by the connecting arm 344. The initial adjustment of the weight 342 50 on its fulcrum arm 341 should be such as to prevent the free unwinding of the web roll 2 when the same is at its largest diameter.

Having thus initially set the brake tensioning 55 means of the pinch rollers at the printing end of the machine and the unwinding brake tension means at the feed end of the machine, the adjustment of the drive means for the feed belt and the conveyor belts for effecting the desired speed of the same in order to provide a slack portion in the 60 web between the feed end and the printing end of the machine will now be described, and thereafter the maintenance of the desired brake tensioning of the feed roller to compensate for its variation in diameter, as affected by said web 65 slack, will be described.

To maintain a constant slack between the unwinding and the printing points of the machine, the surface speed of the unwinding or feed belt 5 should be in coadjusted relation with the 70 surface speed of the printing cylinders 14 and 14', in order to maintain a rate of unwinding of the web 1 from its roll 2 equal to the web consumption of the printing cylinders. The initial step 75 in this direction, as has been pointed out, comprises the selection of a change speed gear 53

(Figs. 3a and 19) having the nearest pitched diameter to effect this result in accordance with the diameter of the printing cylinders used. Since the pitch diameter thus selected still may not provide the exact equality in driving speed 5 desired, a suitable further fine adjustment may be effected by manipulation of the hand wheel 72 (Fig. 1a) which, by moving the belt shifting lever 64 (Figs. 2a and 19), varies the drive ratio between the cooperating tapered pulleys 62 10 and 65.

The slack-tension roller 9 imparts a light tension to the slack web thus provided; and this tension is adjusted, in accordance with the nature of the web material, by manipulation of the hand 15 wheel 318 (Fig. 1a) which winds the convolute spring 317, whose power is transmitted to the pulleys 313 (Fig. 21) and through the connecting straps 312 to the carriages 308 and by these delivered to the slack-tension roller 9 carried thereby. After the proper adjustment is made of the convolute spring 317, it is locked in such position by means of the detent lever 321. Accordingly, a uniform tension is imparted to the slack-tension 20 roller 9 throughout its path of travel. 25

It will be noted that when the diameter of the web roll 2 decreases, it will exert a tendency to increase its unwinding tension and thereby tend to diminish the rate of unwinding of the web 1 therefrom. To counteract or compensate for this 30 variation, the slack-tension roller carriage 308 adjacent the side frame 22, on the drive side of the machine, is connected with the brake tension mechanism of the web roll and serves to vary the 35 said brake tension in accordance with the variations in the rate of web unwinding just described. When the web roll 2 is at its maximum diameter, as at the starting of the machine, the slack-tension roller 9 will be positioned so as to bring the fulcrum roller 324 (Fig. 21) in coaxial 40 alignment with the fulcrum point 328. Accordingly, it will be seen that the weight 325 is in effect a counterweight relative to the weight 342 and as the roller 324 is moved along its fulcrum arm track 326 the weight 325 will be moved in one 45 or the other direction to vary the braking force exerted by the weight 342. The variations of the position of the weight 325 and the corresponding counteraction relative to the weight 342 are transmitted through the fulcrum shaft 328 over the 50 gear 329 and the gear 330 to impart a corresponding moment to the dependent arm 332 by which such variations are transmitted to the cooperating brake adjusting arm 336, thereby transmitting such variations to the brake link 344 55 and causing a proportionate variation between the braking action of the brake band 345 and its cooperating drum 347. Therefore, the action of this mechanism will be to increase or decrease the braking force in accordance with the direction of movement of the weight 325 to thereby 60 vary the unwinding tension of said web 1.

When the rate of unwinding of the web diminishes, the slack-tension roller 9 will be pulled 65 forwardly and this will cause the weight 325 to move in the same direction to thereby produce a counterpressure resulting in relieving the brake force. This will produce a simultaneous reduction in the unwinding tension which will tend to equalize the difference of the unwinding rate 70 and bring the same into synchronism with the rate of web consumption of the printing cylinder. Also, as the diameter of the web roll 2 decreases, an increasing diminution of the brake tension becomes necessary. This is brought 75

about by the tendency of the slack-tension roller 9 to gradually move its normal center in a forward direction. The path of travel of such roller is sufficient to provide for variations between the maximum and minimum diameters of the web roll 2.

The adjustable slight tension exerted on the slack web between the unwinding and printing points of the machine is just sufficient to maintain the web under proper control. Furthermore, the tension resulting from the foregoing will be constantly uniform, independent of the unwinding tension variations of the web roll 2.

Registration

As previously pointed out, each of the printing cylinders is provided with etched configurations on its printing surface and the respective surfaces serve to print component designs in proper registration on the web to produce the composite design, such as a multi-color design. The registration of such designs on the web depends upon the proper co-relation of the designs carried on respective printing cylinders; and accordingly it is essential that the designs on the printing surfaces of said cylinders be adjusted in sharply defined registered relation each to the other. To bring about this condition, the operator next proceeds to adjust the position of the designs on respective printing surfaces in relatively registered position as follows.

The pressure rollers of the respective printing units are lowered to bring the web 1 into printing engagement with respective printing cylinders and a proof is printed. The operator now ascertains from said proof the difference in register between the two complementary impressions. He then makes the coarse adjustment of registration by circumferential adjusting of the surface of the printing cylinder 14' of stage B in the following manner. First the screws such as 151 are loosened (Fig. 12) to thereby loosen the gear periphery such as 150 from its flange such as 148, then the printing surface is moved circumferentially to approximate registration with the printing surface of the preceding stage A; whereupon the screws are tightened and the gear periphery clamped in driving position with its cooperating flange and hub. By manipulation of the control lever 34a (Fig. 1a) the main drive motor 34 (Fig. 2a) is operated at the desired speed so that the machine is now slowly run. The operator observes the register of the printed impressions on the slowly moving web, and the final corrections necessary to effect accurate registration are brought about by operating the hand wheels such as 129 or 132 and 128 until the impressions of the stages A and B, such as the first and second color impressions, are in sharp register.

When further printing stages are employed, the pressure roller of the next succeeding printing unit is brought into engagement with the web and the register difference between the succeeding impressions and the impression of the stage B will be readily ascertained; and adjustments made to the third stage in the manner previously described. Further and successive stages are similarly brought into proper registration.

During the further operation of the machine the register variations will only be of a minute difference and such variations may be corrected by means of the adjusting wheels 129 or 132 and 128 (Figs. 12 and 15) in the manner previously described.

During the operation of the machine it may be

necessary to temporarily interrupt the printing operation while continuing the rotation of the printing cylinders and the reciprocation of the wiping mechanism. In such event the clutch pin 51 (Figs. 2a and 19) is withdrawn and held out of engagement with the worm wheel 41 by engagement of the cross pin 50 in a notch 52 formed on the outer surface of the hub. This disconnects the shaft 48 from the drive shaft 36 and accordingly interrupts the operation of the unwinding belt and the conveyor belts, which are brought to rest while the printing cylinders continue to rotate. When it is desired to resume the printing operation, it is of course desirable that the engagement of the web 1 with the printing surfaces be restored to the identical circumferential position at which point the printing was interrupted. This is desirable in order to maintain a registered position between the printing mechanism and the disposing mechanism of the machine (not shown). In this connection it will be noted that when the pin 48 is reseated in the worm wheel 41, to thereby again connect the driving mechanism of the feed belt and conveyor belts, the relative registered position of the designs on the printing surfaces with respect to the previously printed impressions on the web will be automatically restored by reason of the equal rotative speeds of the worm wheel 41 and the gear 53.

Fluid circulation

The ink and solvent supplying and circulating system will now be described with reference to Figs. 25-31 inclusive; it being understood that in accordance with previous practice herein only the details of one stage will be described in detail as representative of similar operation of each and every stage of the machine.

The pump 388 is started and the valves are set for the operation as illustrated in Fig. 26; it being understood that the ink and solvent reservoirs are supplied with the desired fluids. Accordingly, it will be seen that the solvent valve 382 is closed, the valve 384 is set to place the ink reservoir into communication with the pump through the valve 385 which is closed to the intake supply pipe 386, the valve 390 is adjusted so as to place the pump in communication with the ink chamber while closing the circuit to the drain line and the closed circulating system is completed from the ink chamber through the overflow pipe 398, downwardly through the return pipe 399, and the valve 400, which is closed to the solvent reservoir, through the said valve 400 outwardly through the return inlet port 401 of the ink reservoir 319. Accordingly, the pump will draw the printing fluid from the lowest level in the ink reservoir adjacent to one end wall thereof and will discharge the same through the inlet ports 395 into the ink chamber. The printing fluid will then accumulate in the chamber until the liquid level reaches the top of the overflow pipe 398, after which the overflow of surplus ink will be returned to the ink reservoir 319, entering the same adjacent the top of the said reservoir and adjacent the end thereof opposite to the point at which the ink was drawn out of said reservoir. As previously explained, even if the return line from the chamber to the reservoir should become clogged, the chamber float will come into operation to shut off the circulating pump and to signal the operator.

With the supply and circulating system operating as above described, the printing cylinder 14 is in rotative operation, the printing surface 75

thereof is being charged with printing fluid which is being carried against the doctor which serves to wipe the surface of said cylinder. The surplus printing fluid will be thereby wiped from the printing cylinder and (Figs. 5 and 6) will flow along the lower faces of the doctor 193 and the sealing strip 223, along the inner wall of the supporting bracket 183, from which it will follow down past the deflecting shield 254 on to the lower inclined portion 106 into the body of fluid contained in the ink chamber. Unless proper provision is made to prevent it, there is a marked tendency of any circulating fluid body, of the character involved, to form stagnant portions which will not enter the circulating system until the active fluid body has been exhausted. If not inhibited, this results in periods of stagnation in given areas of the ink body; and during such periods of stagnation the ink body in these areas will settle and become heavier in consistency. The arrangement provided by this invention, as herein described, prevents to a great extent such inactivity or stagnation in the ink bodies of the fountain chamber and reservoir by means of internal currents due to the particular arrangement of the circulating system and the disposition of the intake and outlet ports thereof.

For example, an internal circulation within the fountain chamber is provided by means of the pump 388 which carries the ink from the reservoir and discharges the same in the fountain chamber through the several discharge ports 395 adjacent the lowermost portion of the chamber. The inks entering the chamber in this locality having a certain amount of pressure behind them will prevent the formation of these stagnant areas, which will otherwise produce what is termed a heavy bottom in the fountain chamber, since they sweep the bottom continuously and create a scavenging action upon the same. Furthermore, they force the column of ink in the fountain chamber to rise upwardly and to flow towards the discharge port and thereby create several currents within the fluid column which have been found to be highly beneficial towards increasing the efficiency of the circulating system.

Likewise, the arrangement of the outlet and of the return ports of the reservoir is such as to facilitate an internal circulation within the column of ink contained in such reservoir. The two ports are located at opposite ends of the reservoir and at opposite levels, and consequently the inks returning to the reservoir are forced to travel throughout the length and height of the reservoir before entering the outlet port, thereby creating an internal current which produces an internal agitation of the entire ink body within the reservoir.

It will be noted that by this method of feeding the printing fluid a double circulation is provided, one for the reservoir and the other for the ink chamber. The circulation of printing fluid in the reservoir is produced by drawing the fluid from the bottom level of the reservoir adjacent one end thereof, by returning the fluid to the top level of the reservoir adjacent the other end thereof; and the circulation of the printing fluid in the ink chamber is produced by feeding the fluid to the chamber at the bottom level thereof and by returning it to the top level of the chamber. Furthermore, the rotation of the printing cylinder provides additional agitation. Accordingly, due to this efficient circulation, provision is thus made for constantly maintaining highly efficient agitation for the printing fluid without the use of

any of the usual agitating mechanisms such as have been previously proposed and which have various inherent disadvantages well understood to those skilled in the art.

Should the supply of printing fluid become exhausted, the same may be replenished in the following manner. Referring to Fig. 27, the valve 385 is operated to shut off the ink reservoir 379 and to connect the intake of the pump 388 with a suitable ink supply through the supply pipe 10 386. The additional supply of ink is thereupon discharged into the ink chamber and from there passes back into the reservoir 379. When the proper quantity of printing fluid has been thus obtained, the operator resets the valve 386 to its 15 original position as shown in Fig. 26 and the ink supply will continue as previously described. Replenishing the supply of ink in this manner will be accomplished without interruption to the printing operation. 20

When it is desired to add solvent to the printing fluid during circulation, the valves are set as indicated in Fig. 28, from which it will be seen that the valve 382 is opened and the valve 384 is adjusted to shut off the ink reservoir 379 and 25 to interconnect the reservoir 380 with the pump 388. The solvent is thereupon added in a closed circuit and after the desired quantity has thus been obtained, the valves are reset between normal operating position. 30

When it is desired to clean the fountain chamber and the printing cylinder at the completion of the printing operation, the printing fluid will be completely and efficiently drained from the chamber (Fig. 29) by removing the overflow pipe 398 and allowing the ink to flow out through the drain pipe and valve 400 into the reservoir 379. The valves 384 and 385 remain as in Fig. 26 and the valve 390 is set to drain the lines 391-392 to a suitable receptacle through the drain pipe 40 connected to the valve 390. The overflow pipe 398 is then placed in position (Fig. 30) and the valve 400 is operated to place the overflow pipe in communication with the solvent reservoir 380, the valve 382 is opened and the valves 384 and 45 385 are set to place the said solvent reservoir in communication with the pump, and the valve 390 is set to place the pump in communication with the ink chamber. The pump 388 is now started and the solvent fluid is now circulated in a manner similar to that of the printing fluid already described. The printing cylinder is now rotated to assist in cleaning of the same and more particularly of its printing surface. The solvent so circulated efficiently flushes all of the surfaces 50 of the system previously subjected to the printing ink in normal operation, and the ink film on said surfaces is soft and easily soluble due to the sealed construction of the circulating system; therefore the ink accumulations in the conduits, the pump, 55 the housing and on the printing cylinder will be readily absorbed in the solvent and at the end of the cleaning operation will be found to be free of ink film. At the culmination of such cleaning operation the solvent is returned to the solvent reservoir 380 and the solvent contained in the conduits and the remaining portions of the system will be drained in the same manner as previously described for the printing fluid. 60

During the idle period of the machine the overflow pipe 398 is preferably replaced by a convenient sealing plug (not shown) to prevent evaporation during such idle periods. 65

The solvent thus utilized as a cleaning fluid may be used for solvent purposes within the ink. 70 75

and when thoroughly absorbed with ink will be completely discharged into the ink reservoir 379. The solvent compartment may then be filled with fresh solvent from an outside source of supply 5 by setting the parts as illustrated in Fig. 31, from which it will be seen that the valve 385 is adjusted to place the supply pipe 386, which is now connected to a suitable supply source of solvent, in communication with the pump 388 which then 10 carries the solvent through the valve 390 and the interconnected conduit means into the ink chamber, from which the solvent passes through valve 400, the pipe 402 and thence into the solvent reservoir 380.

15 Should it be desired to use a printing ink of different color, the operator sets the valves 382 and 384 to close the outlet ports of the reservoirs 379 and 380, disconnects the union 387 from the pump 388, disconnects the return valve 400 from 20 the conduit 399 and completely removes the reservoir unit. A new reservoir unit containing a printing fluid of desired color and the desired solvent is then substituted for the removed solvent and ink reservoir means and is similarly 25 connected to the pump and ink chamber through duplicate valve connection mechanism carried by said substitute reservoir.

The reservoir means may be provided with suitable liquid level indicating means, as illustrated in Fig. 1, and preferably also with suitable filtering screens (not shown).

It will be noted that the printing inks used in the art of rotary intaglio printing are usually of the quick drying type and are quite fluid in 35 consistency. Usually they contain solvents of more volatile character than the printing ink used in the art of lithographic or typographic printing. Consequently they tend to quickly evaporate or lose their volatile ingredients 40 when exposed to the outside atmosphere. The constant evaporation of the solvent ingredients of such inks naturally reacts upon the whole mixture or body of ink, which accordingly constantly gains in viscosity. The result of such 45 increase in viscosity may be observed in tone strength of the prints produced, which change in accordance with the varying viscosity of the printing ink. In the production of prints of standard quality it is essential that uniform 50 tone strength be maintained throughout the whole production of the same subject matter and only very slight variations from the proof originally accepted are permitted. This maintenance of uniform tone strength of the prints 55 is consequently regarded in the art as one of the most important requisites to good quality.

The rotary intaglio printing machines in current wide use contain no provisions to retard the free evaporation of the solvent. As a consequence the operator is burdened with the 60 necessity of replenishing the solvent lost by such evaporation; and such replenishment must be accomplished during the printing operation in an endeavor to maintain the equilibrium of 65 tone strength. It has been observed however that the efficiency of this method depends entirely upon the skill and judgment of the operator, and, for this and other reasons, the results produced in this manner are far from satisfactory.

Furthermore, the use of inks having faster 70 drying characteristics than those in current use are very desirable since they permit higher printing speeds, elimination of the heating appliances 75 in the drying system and shorter web distances

between printing zones. The use of such inks heretofore has been considered impractical, for the reason that when exposed to the outside atmosphere they tend to change their consistency so rapidly, due to the increased greater evaporation of their solvent content which therefore results in a handicap rather than in an advantage in efficient press operation.

In the preferred form of apparatus herein illustrated the sealed ink fountain efficiently retards the evaporation of the highly volatile ingredients of such printing inks and renders the use of said inks practical for efficient press operation. By actual practice it has been demonstrated that this construction makes possible the practical operation of a rotary intaglio printing press employing printing inks which contain such highly volatile solvents as petroleum ether, carbon tetrachloride or acetone without observing any operating difficulties resulting from the use of such inks. Furthermore, such construction has made it practical to maintain a uniform tone strength for very long periods of continuous operation, without having to add solvents to such inks, and also to dry the printed web in a considerably shorter distance and time than now is in vogue and without the aid of heating appliances such as currently used. It has also been observed that, due to the character of rapidly setting inks of this type, the prints produced are considerably sharper and smoother in tone, which is a very desirable characteristic. The total result provides a very marked improvement over the present methods and constructions as regards speed of printing, efficiency of operation and quality of prints so produced.

It will be noted that in the apparatus employed the printing cylinder, the reciprocating doctor knife and the ink chamber employed are 40 adapted to perform the same primary function as elements of this general character perform in rotary intaglio printing presses in current use; and further than this these elements perform an additional or secondary function, with 45 the aid of auxiliary sealing extensions of the walls in cooperation with the housing. In this secondary function they constitute elements for the sealing of the ink chamber. It will be further noted that the dual function of these elements does not in any way handicap them in their usual functions nor does such combination of such elements in any way complicate or render more difficult the operation of the printing press. Such apparatus serves to relieve the operator of constant worry and vigilance concerning the maintenance of uniform tone strength and therefore enables him to give his full attention to other duties and thereby increases 50 his efficiency.

It will be understood that while the contact surface 246 of the sealing shutter 244 (Fig. 5) in the construction shown is preferably of resilient material to reduce the wear and to prevent the scoring of the printed cylinder, nevertheless 65 it may be desirable in some cases to use a firm material for such contact surface and to adjust the sealing edge thereof in slightly spaced relation with the printing surface so as to assume a position of sealing contiguity therewith. However, the sealing efficiency of the alternative construction will not be as efficient as that illustrated in the preferred embodiment.

It is to be further understood that in addition to the sealing effect produced by the cooperative 75

arrangement and position of the parts such as the printing cylinder, the reciprocating doctor knife and the fountain housing and parts associated therewith, some of said elements comprise other useful functions providing advantages apart from their sealing functions, and accordingly are to such extent useful in intaglio printing presses which do not employ sealed ink housings. For example, it might be pointed out that the flexible strip (Fig. 5) 223, by reason of its pressure engagement with the lower face of the doctor knife adjacent to its wiping edge, tends to maintain said edge uniformly flat throughout its entire length and further deflects the wiped ink from the lower face of said doctor. As a result the wiping efficiency and cleanliness of the wiping mechanism is thereby enhanced. Also the semi-cylindrical housing extension blocks such as 221—222 afford a means of support for the ends of the reciprocating doctor beyond the respective ends of the printing cylinder. This serves to prevent the rounding off of the printing surface at its respective ends and thereby serves to further promote a clean wipe of the whole printing surface. Other advantages of construction and operation resulting from the invention will be obvious to those skilled in the art.

Referring to Fig. 5, attention is called to what is commercially called a wiping angle of the doctor knife in a rotary intaglio printing machine. The wiping angle herein illustrated as W is the angle formed between the plane of the doctor and a plane XY passing through the axis of the cylinder and the contact edge of the doctor with the surface of the printing cylinder. It will be noted that in the present embodiment the wall portion 185, which serves as the supporting means for the doctor, is positioned to be parallel to the plane YY . The purpose for this arrangement is to provide a means whereby the wiping angle W will remain constant when the doctor supporting bracket 183 is adjusted upwardly or downwardly along the wall portion 185 to provide for printing cylinders of varying diameters.

It will be noted that in the method practiced according to this invention the ink supplied to the printing chamber is being constantly maintained, the rotating printing surface is being coated with ink, the coated surface is being brought to the wiping position, the surplus ink is being wiped from the printing surface and returned to the body of ink within the sealed compartment, and there is thereby provided a closed circuit in which the ink is in continuous circulation and under continuous agitation and, except for the ink that is actually transferred from the printing surface to the web, said ink is at all times maintained within the closed circuit to thereby prevent evaporation of its volatile ingredients. As a result the body consistency of said ink is constantly preserved and the uniformity of tone strength is thereby maintained in an efficient, practical and economical manner.

In this connection it is to be particularly noted that the mere use of highly volatile inks with rapid or continuous circulation in open fountains would be impractical, since, in addition to the increased evaporation inherent in such inks, such circulation would increase the rate of evaporation; and therefore there is a particularly close cooperative association between the closed fountain and fluid circulating mechanisms in providing a closed system functioning as a unitary whole. The closed fountain makes the use of such inks commercially practical, and the circulating sys-

tem serves to greatly enhance the benefits derived from the use of such inks in a closed fountain; and used in combination each supplements the other in the resultant closed circuit system.

In addition to the several advantageous features of the machine, as already described, it will be noted that the superimposed disposition of its printing units results in an economy of floor space, and that the inwardly staggered disposition of the superimposed printing units provides free access and comfortable supervision of the several units for the operator. Furthermore the close grouping of the operating and control handles and hand wheels, on one side of the machine, the large openings of the frame work, the compact arrangement and comparatively short construction of the whole machine, result in a quick and comfortable supervision of the operation of the machine by the operator and greatly enhances the productivity of the machine.

It will be further noted, that the similarity of the several superimposed printing units results in an economy of construction cost and provides for readily building a machine having the desired number of printing stages.

It will also be noted (Figs. 1 and 1a) that the main drive motor 34, its speed controller 34a, the blowers such as 418, the air ducts such as 421, the ink and solvent reservoirs such as 317, their pumps such as 388, and their motor such as 408, are located within the floor space of the base plate 20 of the machine. This disposition of the appliances, which heretofore were usually spaced from the machine, and seriously obstructed the approachability to the machine, in this invention results in an increased economy of floor space and greater accessibility.

The maintenance of uniform tension of the web in the machine improves the register maintenance and thereby increases the productivity of said machine.

The elimination of the usual heating appliances in the drying system, prevents web distortions. The shortened linear web distance between the impression points of the machine combined with the beneficial effects of the conveyor belts, are very helpful for the maintenance of sharp register. The elimination of the heating appliances furthermore reduces the cost of construction and the elimination of their maintenance results in lowered operating cost. The prevention of evaporation of the solvents, by means of the sealed fountain construction, further reduces the operating cost of the machine.

The single base plate, the interlocking frame work, the frictionless drive supports, the interlocking gear train and its efficient lubrication results in a smooth, vibrationless and torsionless drive action, highly important for fast printing speeds and greatly reduces power consumption.

The utilization of the tie shafts for the frames, the supporting shaft of the fountain housings and the fountain walls of the fountain housings for a multiplicity of uses, results in an economy of construction cost, a greater simplicity of design, and added accessibility.

Various modifications may be made in the machine and the present exemplification is to be taken as illustrative and not limitative thereof.

Having thus described my invention with particularity with reference to the preferred method of carrying out the same and in connection with the preferred apparatus for carrying out the same, it will be obvious to those skilled in the art, after understanding my invention, that other

changes and modifications may be made therein without departing from the spirit and scope of my invention, and I aim in the appended claims to cover such changes and modifications as are 5 within the scope of the invention.

What I claim is:

1. In a rotary intaglio printing press, the combination of an ink housing, a rotatable printing cylinder having a portion of its periphery within 10 said housing for the application of ink thereto, wiping means comprising a reciprocable doctor knife normally in wiping engagement with said cylinder, and closure means cooperating with said doctor knife and said housing and said cylinder 15 for preventing substantial evaporation of said ink, said closure means comprising a relatively stationary sealing element constituting a sealing extension of said doctor knife during the reciprocation thereof.
  2. In a rotary intaglio printing press, the combination of an ink housing, a rotatable printing cylinder having a portion of its periphery within 20 said housing for the application of ink thereto, wiping means comprising a reciprocable doctor knife normally in wiping engagement with said cylinder, and closure means cooperating with said doctor knife and said housing and said cylinder 25 for preventing substantial evaporation of said ink, said closure means comprising a flexible closure element in sealing engagement with 30 said doctor knife and with other adjacent closure members.
  3. In a rotary intaglio printing press, the combination of an ink housing, a rotatable printing 35 cylinder having a portion of its periphery within said housing for the application of ink thereto, a reciprocable doctor normally in wiping engagement with said cylinder on one side of the printing zone, and closure means cooperating with 40 said doctor and said housing and said cylinder for preventing substantial evaporation of said ink, said closure means comprising means extending 45 axially of said cylinder and in sealing continuity with the periphery of said cylinder and an adjacent portion of said housing on the opposite side of said printing zone.
  4. In a rotary intaglio printing press, the combination of an ink housing, a rotatable printing cylinder having a portion of its periphery within 50 said housing for the application of ink thereto, a reciprocable doctor normally in wiping engagement with said cylinder, and means cooperating with said doctor and said housing and said cylinder for preventing substantial evaporation of 55 said ink, said means comprising a sealing member extending longitudinally of said doctor in sealing continuity therewith, said doctor and said sealing member extending beyond the ends of 60 said cylinder, and said sealing member having its median portion intermediate its said extending ends cut away and free of contact with the printing surface of said cylinder.
  5. In a rotary intaglio printing press, the combination of an ink housing, a rotatable printing 65 cylinder having a portion of its periphery within said housing for the application of ink thereto, a reciprocable doctor normally in wiping and sealing engagement with said cylinder, and supplemental sealing means cooperating with said 70 doctor and said housing and said cylinder for preventing substantial evaporation of said ink, said supplemental sealing means comprising a sealing member extending longitudinally of said doctor beyond the extremities of the path of 75 travel of said doctor and in sealing engagement
- with said doctor adjacent the ends of said doctor during said reciprocation and being spaced away from said cylinder throughout the length of said cylinder.
6. In a rotary intaglio printing press, the combination of an ink housing having end walls, a rotatable printing cylinder having a portion of its periphery within said housing for the application of ink thereto and having its ends spaced inwardly from said end walls, and members providing inwardly projecting extensions of said end walls in respective sealing contiguity with said end walls and adjacent cylinder ends.
7. In a rotary intaglio printing press, the combination of an ink housing having end walls, a rotatable printing cylinder having a portion of its periphery within said housing for the application of ink thereto and having its ends spaced inwardly from said end walls, and members providing independently adjustable and removable inwardly projecting extensions of said end walls and in respective sealing contiguity with said end walls and adjacent cylinder ends, to thereby provide for printing cylinders of varying size.
8. In a rotary intaglio printing press, the combination of an ink housing, a rotatable printing cylinder having a portion of its periphery within said housing for the application of ink thereto, wiping means comprising a reciprocable doctor normally in wiping engagement with said cylinder, and sealing means cooperating with said doctor and said housing and said cylinder for preventing substantial evaporation of said ink, said sealing means comprising a member in sealing engagement with said wiping means and extending beyond the ends of said cylinder, and means at the ends of said cylinder in sealing contiguity therewith and in sealing engagement with said sealing member.
9. In a rotary intaglio printing press, the combination of an ink housing having side walls and end walls, a rotatable printing cylinder having a portion of its periphery within said housing for the application of ink thereto, wiping means comprising a reciprocable doctor in wiping engagement with the periphery of said cylinder, said wiping means having a sealing engagement with adjacent side and end wall portions of said housing, and supplemental sealing means cooperating with said housing and said printing cylinder to arrest the substantial evaporation of said ink from said housing.
10. In a rotary intaglio printing press, the combination of an ink housing having end walls, a rotatable printing cylinder having a portion of its periphery within said housing for the application of ink thereto, a reciprocable doctor normally in wiping engagement with said cylinder, a flexible strip in sealing engagement with said doctor and extending beyond the ends of said cylinder, means at the respective ends of said cylinder in sealing contiguity therewith and with respectively adjacent end walls and in sealing engagement with said flexible strip, said flexible strip being relatively stationary longitudinally and having its ends in sealing contiguity with the inner walls of respective ends of said housing and supplemental sealing means, said strip and said end sealing means and said supplemental sealing means cooperating with said doctor and said housing and said cylinder for preventing substantial evaporation of said ink.
11. In a rotary intaglio printing press, the combination of an ink housing having end walls, a rotatable printing cylinder having a portion of

its periphery within said housing for the application of ink thereto and having its ends spaced away from said end walls to provide end spaces, a reciprocable doctor normally in wiping and sealing engagement with said cylinder and having its ends projecting beyond the ends of said cylinder, and sealing means cooperating with said doctor and said housing and said cylinder for preventing substantial evaporation of said ink, said sealing means comprising end seals positioned in respective of said spaces in sealing contiguity with respective ends of said cylinder, and flexible means in sealing engagement with said doctor and in continuous operative sealing engagement with said end seals.

12. In a rotary intaglio printing press, the combination of an ink housing having end walls, a rotatable printing cylinder having a portion of its periphery within said housing for the application of ink thereto and having its ends spaced away from said end walls to provide end spaces, wiping means comprising a reciprocable doctor normally in wiping and sealing engagement with said cylinder and having its ends projecting beyond the ends of said cylinder, and sealing means cooperating with said doctor and said housing and said cylinder for preventing substantial evaporation of said ink, said sealing means comprising end seals positioned in respective of said spaces in sealing contiguity with respective ends of said cylinder and adjustable transversely of the axis of said cylinder, and a sealing member in sealing engagement with said wiping means and in sealing engagement with said end seals.

13. In a rotary intaglio printing press, the combination of an ink housing having end walls, a rotatable printing cylinder having a portion of its periphery within said housing for the application of ink thereto and having its ends spaced away from said end walls to provide end spaces, wiping means comprising a reciprocable doctor normally in wiping and sealing engagement with said cylinder and having its ends projecting beyond the ends of said cylinder, and sealing means cooperating with said doctor and said housing and said cylinder for preventing substantial evaporation of said ink, said sealing means comprising end seals of arcuate form positioned in respective of said spaces in sealing contiguity with respective ends of said cylinder and of substantially the same radius of curvature as said cylinder, and a sealing member in sealing engagement with said wiping means and in sealing engagement with the curved surfaces of said end seals.

14. In a rotary intaglio printing press, the combination of an ink housing having side walls and end walls, a rotatable printing cylinder having a portion of its periphery within said housing for the application of ink thereto and having its ends spaced inwardly from the end walls and its periphery spaced inwardly from said side walls of said housing, wiping means comprising a reciprocable doctor normally in wiping engagement with said cylinder and positioned adjacent one of said side walls, means for preventing substantial evaporation of ink from said housing comprising sealing means engaging said wiping means, end members positioned respectively between said cylinder ends and said end walls and in sealing contiguity with said sealing means and said cylinder ends, and second sealing means positioned adjacent said other side wall and serving to bridge the space between said side wall and cylinder periphery contiguous thereto and having its ends adjacent respectively to said end members, and means for adjusting said bridging means transverse the axis of said cylinder.

15. In a rotary intaglio printing press, the combination of an ink housing having side walls and end walls, a rotatable printing cylinder having a portion of its periphery within said housing for the application of ink thereto and having its ends spaced inwardly from the end walls and its periphery spaced inwardly from said side walls of said housing, wiping means comprising a reciprocable doctor normally in wiping engagement with said cylinder and positioned adjacent one of said side walls, means for preventing substantial evaporation of ink from said housing comprising sealing means engaging said wiping means, end members positioned respectively between said cylinder ends and said end walls and in sealing contiguity with said sealing means and said cylinder ends, a felt sealing strip positioned adjacent said other side wall forming an extension in said side wall and in sealing engagement with the periphery of said cylinder and having its ends adjacent respectively to said end members.

16. In a rotary intaglio printing press, the combination of an ink housing having side walls and end walls, a rotatable printing cylinder having a portion of its periphery within said housing for the application of ink thereto and having its ends spaced inwardly from the end walls and its periphery spaced inwardly from said side walls of said housing, wiping means comprising a reciprocable doctor normally in wiping engagement with said cylinder and positioned adjacent one of said side walls, means for preventing substantial evaporation of ink from said housing comprising sealing means engaging said wiping means, end members positioned respectively between said cylinder ends and said end walls and in sealing contiguity with said sealing means and said cylinder ends and independently adjustable transverse the axis of said cylinder, means positioned adjacent said other side wall and serving to bridge the space between said side wall and cylinder periphery contiguous thereto and having its ends adjacent respectively to said end members, and means for adjusting said bridging means transverse the axis of said cylinder.

17. In a rotary intaglio printing press, the combination of an ink housing having a side wall portion hinged, a rotatable printing cylinder having a portion of its periphery within said housing for the application of ink thereto, and a doctor slidably supported on said hinged wall portion for reciprocation longitudinally of said cylinder.

18. In a rotary intaglio printing press, the combination of an ink housing having a side wall portion hinged, a rotatable printing cylinder having a portion of its periphery within said housing for the application of ink thereto, a doctor slidably supported on said hinged wall portion for reciprocation axially of said cylinder and adjustable up and down relative to said hinged portion and movable with said hinged portion, said hinged wall portion in normal operating position lying in a plane substantially parallel to a plane extending from the axis of said cylinder to the line of normal contact of the doctor and cylinder.

19. In a rotary intaglio printing press, the combination of an ink housing having end walls and side walls, a rotatable printing cylinder having a portion of its periphery within said housing for the application of ink thereto, bracket means adjustably mounted upon an upwardly projecting

continuation of one of said side walls and providing a support for a doctor, said bracket being in sealed relationship with said end walls and said side wall, a doctor slidably mounted on said bracket support for reciprocation relative thereto, and additional sealing means carried by and sealed to said bracket in sealing engagement with said doctor and said end walls.

20. In a rotary intaglio printing press, the combination of an ink housing having end walls and side walls, a rotatable printing cylinder having a portion of its periphery within said housing for the application of ink thereto, bracket means adjustably mounted upon an upwardly projecting portion of one of said side walls and providing a support for a doctor, said bracket being in sealed relationship with said end walls and said side wall, a doctor slidably mounted on said support for reciprocation relative thereto, means for sealing the ends of said cylinder relative to said end walls, and additional sealing means carried by and sealed to said bracket and in sealing engagement with said doctor and said end sealing means.

21. In a rotary intaglio printing press, the combination of an ink housing having end walls and side walls, one of said side walls having a hinged portion, a rotatable printing cylinder having a portion of its periphery within said housing for the application of ink thereto, bracket means adjustably mounted upon said hinged portion and providing a support for a doctor, a doctor slidably mounted on said support for reciprocation relative thereto, means for sealing said bracket relative to said end walls and said side wall portion, and additional sealing means carried by said bracket and in sealing engagement with said doctor.

22. In a rotary intaglio printing press, the combination of an ink housing having side walls and end walls, a rotatable printing cylinder having a portion of its periphery within said housing for the application of ink thereto and having its ends spaced respectively from said end walls and its printing surface spaced from said side walls to provide end spaces and side spaces, a reciprocable doctor normally in wiping engagement with said cylinder, means bridging said end spaces and extending from contiguous said end walls to contiguous said cylinder ends, and means bridging said side spaces and extending from contiguous said side walls to contiguous said printing surface, said last means including said doctor, and said end and side bridging means lying in substantial contiguous continuity.

23. In a rotary intaglio printing press, the combination of an ink housing having cooperating side walls and end walls, a rotatable printing cylinder having a portion of its periphery within said housing for the application of ink thereto, a side wall portion of said housing being removable from its normal position, a reciprocable doctor positioned adjacent the upper part of said wall portion and normally in wiping engagement with said cylinder when said wall portion is in its normal position and serving as a part of closure means for said housing, and additional closure means for said housing, said housing and said doctor and said cylinder and said additional closure means serving to substantially retard the escape of ink fumes from said housing.

24. In a rotary intaglio printing press, the combination of an ink housing having cooperating side walls and end walls, a rotatable printing cylinder having a portion of its periphery within said housing for the application of ink thereto,

said end walls providing structural supporting means for said cylinder, a side wall portion of said housing being removable from its normal position, a reciprocable doctor positioned adjacent the upper part of said wall portion and normally in wiping engagement with said cylinder when said wall portion is in its normal position and serving as a part of closure means for said housing, and additional closure means for said housing, said housing and said doctor and said cylinder and said additional closure means serving to substantially retard the escape of ink fumes from said housing.

25. In a rotary intaglio printing press, the combination of an ink housing having side walls and end walls, a rotatable printing cylinder having a portion of its periphery within said housing for the application of ink thereto and having its ends spaced respectively from said end walls and its printing surface spaced from said side walls to provide end spaces and side spaces, a doctor normally in wiping engagement with said cylinder and slidably supported adjacent one of said side walls for reciprocation lengthwise of said cylinder, and sealing means comprising extensions from said side and end walls bridging said spaces and cooperating with said doctor and said housing and said cylinder for preventing substantial evaporation of said ink.

26. In a rotary intaglio printing press, the combination of an ink housing, comprising a structural supporting frame and having end walls and side walls, a rotatable printing cylinder having a portion of its periphery within said housing for the application of ink thereto and having its ends spaced respectively from said end walls and its printing surface spaced from said side walls, a doctor normally in wiping engagement with said cylinder, means for slidably supporting said doctor from said frame for reciprocation axially of said cylinder, and sealing means comprising extensions carried by said frame and bridging said spaces and cooperating with said doctor and its supporting means and said housing and said cylinder in sealing contiguity for preventing substantial evaporation of said ink.

27. In a rotary intaglio printing press, the combination of an ink housing comprising a structural supporting frame and having end walls and side walls, a rotatable printing cylinder having a portion of its periphery within said housing for the application of ink thereto and having its ends spaced respectively from said end walls and its printing surface spaced from said side walls, a doctor normally in wiping engagement with said cylinder, means for slidably supporting said doctor from said frame for reciprocation axially of said cylinder, sealing means comprising extensions carried by said frame and bridging said spaces and cooperating with said doctor and its supporting means and said housing and said cylinder in sealing contiguity for preventing substantial evaporation of said ink, and means for adjusting said bridging means to accommodate printing cylinders of varying size.

28. In a rotary intaglio printing press, the combination of an ink housing, a rotatable printing cylinder having a portion of its periphery within said housing for the application of ink thereto, a reciprocable doctor adjacent a wall of said housing in advance of the printing zone and normally in wiping engagement with the printing surface of said cylinder, a sealing shutter supported adjacent the opposite side of said housing and provided with an inwardly project-

ing longitudinal edge pressure-held against the printing surface of said cylinder, and means to quickly disengage said shutter edge from said cylinder surface.

29. In a rotary intaglio printing press, the combination of an ink housing, a rotatable printing cylinder having a portion of its periphery within said housing for the application of ink thereto, a reciprocable doctor adjacent a wall of 10 said housing in advance of the printing zone and normally in wiping engagement with the printing surface of said cylinder, a sealing shutter pivotally supported adjacent the opposite side of said housing and provided with an inwardly 15 projecting longitudinal edge in contact with the printing surface of said cylinder, the line of contact of said edge with said surface being positioned below the pivot point of said shutter.

30. In an intaglio printing press, the combination of a reciprocable slide, a doctor carried by and reciprocable with said slide, cam stud means in driving connection with said slide and extending transversely thereto, a cam in cooperative driving engagement with said stud means, 25 means for rotating said cam to effect the reciprocation of said doctor, and pivotal means on which said doctor and said slide and said cam are mounted for movement of said doctor thereabout while maintaining driving connection between 30 said cam and said doctor.

31. In an intaglio printing press, the combination of a reciprocable slide, a doctor carried by and reciprocable with said slide, a cam in cooperative driving engagement with said slide, means 35 for rotating said cam to effect the reciprocation of said doctor, and means about which said doctor and said slide and said cam and said interconnected driving means are rotatable while maintaining said cooperative driving engagement.

32. In an intaglio printing press, the combination of a fountain housing having a hinged wall member and a wall member relatively stationary thereto, a reciprocable doctor, driven means for reciprocating said doctor, said doctor and driven means being adjustably supported on said hinged member, driving means cooperating with said driven means for reciprocating said doctor, said driving means being supported on said stationary 45 wall member and adapted to be in driving engagement with said driven means throughout adjusted positions of said doctor and driven means relative to said hinged member when the hinged wall member is in its operative position.

33. In a rotary intaglio printing press, the combination of a housing having a liquid chamber serving as a sub-receptacle for a printing ink, a rotatable printing cylinder having a portion of its periphery within said housing and extending within said chamber, means cooperating with said housing and said cylinder for preventing substantial evaporation of the volatile ingredients from said ink, a supply reservoir for said ink, 60 means to continuously withdraw said ink from said reservoir and discharge the same adjacent the bottom of and into said liquid chamber in an amount in excess of the ink required in printing, means to maintain the ink at a predetermined 65 level in said chamber relative to a portion of the said cylinder to be submerged therein, and means to continuously return said excess ink from the top of said liquid level in said chamber to said reservoir, to thereby maintain continuous circulation of said ink and prevent substantial evaporation thereof during the operating 70 period of said press.

34. In a rotary intaglio printing press, the combination of a housing having a liquid chamber serving as a sub-receptacle for a printing ink, 5 a rotatable printing cylinder having a portion of its periphery within said housing and extending within said chamber, means cooperating with said housing and said cylinder for preventing substantial evaporation of the volatile ingredients from said ink, a supply reservoir for said ink, 10 means to continuously withdraw said ink from said reservoir and discharge the same adjacent the bottom of and into said liquid chamber in an amount in excess of the ink required in printing, 15 means to maintain the ink at a predetermined level in said chamber relative to a portion of said cylinder to be submerged therein, means to continuously return said excess ink from the top of said liquid level in said chamber to said reservoir, to thereby maintain continuous circulation of said ink and prevent substantial evaporation thereof during the operating 20 period of said press.

35. In a rotary intaglio printing press, the combination of a housing having a liquid chamber serving as a sub-receptacle for a printing ink, 30 said chamber being provided with a plurality of inlet ports disposed adjacent the bottom thereof, a rotatable printing cylinder having a portion of its periphery within said housing and extending within said chamber, means cooperating with said housing and said cylinder for preventing substantial evaporation of the volatile ingredients from said ink, a supply reservoir for said ink, 35 means to continuously withdraw said ink from said reservoir and discharge the same through said ports and into said liquid chamber in an amount in excess of the ink required in printing, means to maintain the ink at a predetermined level in said chamber relative to a portion of the periphery of said cylinder to be submerged therein, and means to continuously return said excess ink from the top of said liquid level in said chamber to said reservoir, to thereby maintain continuous circulation of said ink and prevent substantial evaporation thereof during the operating 40 period of said press.

36. In a rotary intaglio printing press, the combination of a housing having a liquid chamber serving as a sub-receptacle for a printing ink, 55 a rotatable printing cylinder having a portion of its surface within said housing and extending within said chamber, means cooperating with said housing and said cylinder for preventing substantial evaporation of the volatile ingredients from said ink, a supply reservoir for said ink, 60 having a discharge port adjacent the bottom and one end thereof and a return port adjacent the top and the other end thereof, means to continuously withdraw ink from the lower portion of said reservoir through said discharge port and to feed the same into the said liquid chamber, and means to continuously return ink from said chamber through said return port to the upper portion of said reservoir.

37. In a rotary intaglio printing press, the combination of a housing having a liquid chamber which serves as a sub-receptacle for a printing ink, a rotatable printing cylinder having a portion of its periphery within said housing and extending within said chamber, means cooperat-

- ing with said housing and said cylinder for preventing substantial evaporation of the volatile ingredients from said ink, said chamber being provided with a plurality of charging ports located along its bottom portion and having a discharge port located a level higher than the uppermost of said charging ports to thereby provide a constantly varying ink supply in said chamber, a reservoir for the main supply of ink having a discharge port located adjacent one end and adjacent the bottom portion of said reservoir and having a return port located adjacent the opposite end and adjacent the uppermost level of the ink in said reservoir, means for charging said liquid chamber from said discharge port of said reservoir, and means for returning ink from said fountain chamber to said reservoir, whereby continuous circulation of ink is provided from the bottom of the reservoir to the bottom of the liquid chamber and from the top ink level of said chamber to the top ink level of the reservoir while preventing substantial evaporation of said ink.
38. In a rotary intaglio printing press, the combination of a housing having a liquid chamber, a rotatable printing cylinder having a portion of its periphery within said housing and extending within said chamber, means cooperating with said housing and said cylinder for preventing substantial evaporation of the volatile ingredients from said ink, an ink reservoir, a solvent reservoir, conduit means for charging said chamber and common to both of said reservoirs, means selectively operable to individually withdraw one of said liquids from its reservoir and for discharging the same through said common conduit means and into said chamber, and means selectively operable to return liquid from said chamber to either of said reservoirs.
39. In a rotary intaglio printing press, the combination of an ink housing, a rotatable printing cylinder having a portion of its periphery within said housing for the application of ink thereto, means for wiping ink from the periphery of said cylinder, means including said housing and said wiping means and said cylinder for retarding the escape from said housing of volatile ingredients of said ink, a substantially sealed supply reservoir for said ink to retard the escape of volatile ingredients therefrom, and means in sealed communication with said housing and said reservoir for circulating ink between said housing and said reservoir.
40. In the art of intaglio printing, the method of sustaining uniform tone strength of prints which comprises subjecting an intaglio printing surface comprising engraved and unengraved portions to an application of an ink containing volatile ingredients while continuously circulating a body of said ink between a main liquid body spaced from said printing surface and a secondary liquid body in surface contact with said printing surface, preventing substantial evaporation of said ingredients from the main liquid body and the secondary liquid body during such circulation, wiping the unengraved portions of said printing surface prior to the time of exposure to substantial evaporation of the ink remaining in said unengraved portions and returning the excess ink from said wipe to said circulating body of ink, momentarily exposing to substantial evaporation the ink remaining in the engraved portions of the printing surface and immediately thereafter transferring said exposed ink from

said engraved portions to a surface to be printed upon.

41. In a rotary intaglio printing press, the combination of a pair of longitudinally extending spaced apart supporting frames, a plurality of transversely extending members supported by said frames, fountain housing means supported by said members, an intaglio printing cylinder rotatably journaled in and supported by said housing means, and wiping mechanism for said cylinder pivotally supported from one of said transversely extending members.

42. In a rotary intaglio printing press, the combination of a pair of longitudinally extending spaced apart supporting frames, a plurality of transversely extending members supported by said frames, one of said members being axially movable to provide an adjusting shaft, fountain housing means supported by said members and attached to said shaft for movement thereby, an intaglio printing cylinder rotatably journaled in and supported by said housing means and movable with said housing, and means to axially move said shaft.

43. In a rotary intaglio printing press, the combination of a rotatable printing cylinder having outwardly extending hubs on respective ends thereof, a drive shaft for said cylinder positioned in said hubs and extending therethrough and detachably connected thereto for ready removal therefrom, a pair of spaced apart supporting walls in which said shaft is journaled and through which said shaft is adapted to be axially inserted and removed in mounting and dismounting said cylinder, and cylinder supporting means extending inwardly from said respective supporting walls and spaced slightly below respective peripheries of said cylinder hubs when said cylinder is in normal operative position and adapted to support said cylinder when said shaft is withdrawn therefrom.

44. In a rotary intaglio printing press, the combination of a rotatable printing cylinder having outwardly extending hubs on respective ends thereof, a drive shaft for said cylinder positioned in said hubs and extending therethrough and detachably connected thereto for ready removal therefrom, a pair of spaced apart supporting walls in which said shaft is journaled and through which said shaft is adapted to be axially inserted and removed in mounting and dismounting said cylinder, and cylinder supporting means extending inwardly from said respective supporting walls and spaced slightly below respective peripheries of said cylinder hubs when said cylinder is in normal operative position and adapted to support said cylinder when said shaft is withdrawn therefrom, said cylinder supporting means comprising a plurality of downwardly curved projections on each supporting wall providing multi-point contact support for each hub and serving to freely drain printing fluid from the supporting surfaces of said projections.

45. In a printing machine, an ink fountain, an intaglio printing cylinder rotatable in the fountain, fountain components hingedly and movably secured to the fountain to substantially close the fountain around the greater portion of the cylinder and to permit the removal of the cylinder from the fountain.

46. In a rotary intaglio printing press, the combination of a rotary intaglio printing cylinder, ink housing means within which is positioned a portion of the periphery of said cylinder for the application of ink thereto, said housing means

- and said cylinder providing an enclosure adapted to prevent substantial evaporation of the volatile ingredients from said ink, wiping mechanism comprising a reciprocable doctor, said housing means comprising a wall bracket pivotally supported adjacent a side wall of said housing and forming an upward extension of said wall and serving to support said wiping mechanism.
47. In a rotary intaglio printing press, the combination of a rotary intaglio printing cylinder, ink housing means within which is positioned a portion of the periphery of said cylinder for the application of ink thereto, said housing means and said cylinder providing an enclosure adapted to prevent substantial evaporation of the volatile ingredients from said ink, wiping mechanism comprising a reciprocable doctor, said housing means comprising an upwardly and downwardly adjustable wall bracket pivotally supported adjacent a side wall of said housing and forming an upward extension of said wall and serving to support said wiping mechanism.
48. In a rotary intaglio printing press, the combination of a rotary intaglio printing cylinder, ink housing means for the application of ink to said cylinder and for the wiping of said ink from said cylinder, said housing means forming an en-
- closure around the major portion of said cylinder adapted to prevent the substantial evaporation of the volatile ingredients of said ink, said housing means comprising a side wall and a wall bracket for the support of a wiping mechanism, 5 said wall bracket constituting a pivotal extension of said side wall and having a sealing relationship with said side wall when said wall bracket is occupying its normal operating position.
49. In a rotary intaglio printing press, the combination of a rotary intaglio printing cylinder, ink housing means within which is positioned a portion of the periphery of said cylinder for the application of ink thereto, said housing means and said cylinder providing an enclosure adapted to 10 prevent substantial evaporation of the volatile ingredients from said ink, wiping mechanism comprising a reciprocable doctor, said housing means comprising a wall bracket pivotally supported adjacent a side wall of said housing and 15 forming an upward extension of said wall and serving to support said wiping mechanism, said side wall having a sealing engagement with said wall bracket when the latter occupies its normal 20 operating position.

25 ADOLPH WEISS.

DISCLAIMER

2,055,272.—*Adolph Weiss*, Brooklyn, N. Y. ROTARY INTAGLIO PRINTING. Patent dated September 22, 1936. Disclaimer filed June 25, 1940, by the inventor. Hereby enters this disclaimer to claims 38, 39, 40, and 45 in said specification. [Official Gazette July 30, 1940.]
